(57) **ABSTRACT**

Provided is a flush toilet capable of increasing the volume of a waste conveyance flow for washing down waste thereby improving a waste conveyance capability. The flush toilet includes: a discharge conduit (16) communicated with the discharge trap pipe. The discharge conduit includes: a flow dividing section (26) and a delaying flow passage (28) branched from the flow dividing section. The flow dividing section has a guide portion (32) configured to guide relatively low-speed flush water along the guide portion to the delaying flow passage. The delaying flow passage (28) is configured such that flush water having flowed into the delaying flow passage along the guide portion (32) is enabled to merge with a flush water flow reaching the flow dividing section at a timing after the inflow of the flush water to the delaying flow passage.

FLUSH TOILET

TECHNICAL FIELD

The present invention relates to a flush toilet, and more particularly to a flush toilet designed to be flushed using flush water to discharge waste.

BACKGROUND ART

Heretofore, there has been known a discharge socket for connecting a drain passage of a toilet main unit of a flush toilet and an underfloor drain pipe, as disclosed in Patent Document 1 (JP 2011-179187A). This discharge socket has: a toilet main unit-side connecting pipe member configured to be connected to an outlet of the drain passage of the toilet main unit; an underfloor-side connecting pipe member configured to be connected to an inlet of the underfloor drain pipe; and an approximately linearly-extending intermediate pipe member connecting the toilet main unit-side connecting pipe member and the underfloor-side connecting pipe member.

In a flush toilet equipped with this discharge socket, when toilet flushing is started to discharge waste in a bowl portion from a toilet main unit, part of flush water stored in the bowl portion firstly flows, as leading flush water flowing on a leading side of the waste, from a drain passage into the discharge socket and then flows toward a building sewer pipe. Subsequently, a flow of flush water flowing mainly on a trailing side of the waste to convey the waste, i.e., a waste conveyance flow, flows into the discharge socket and then flows toward the building sewer pipe together with the waste.

SUMMARY OF INVENTION

Technical Problem

Meanwhile, the flush toilet as described in the Patent Document 1 is requested to reduce the volume of flush water to be used per toilet flushing cycle, in order to cope with demand for water-saving. In this case, the volume of the waste conveyance flow flowing on the trailing side of the waste to convey the waste will also be reduced. The reduction in volume of the waste conveyance flow is likely to cause deterioration in waste conveyance capability (capability of conveying waste), e.g., a reduction in distance over which it is possible to convey waste through a transversely-extending conduit.

The present invention has been made to solve the above conventional problem, and an object thereof is to provide a flush toilet capable of increasing the volume of a waste conveyance flow for washing down waste, even when the volume of flush water for toilet flushing is reduced in order to cope with demand for water-saving, thereby improving a waste conveyance capability.

Solution to Problem

In order to achieve the above object, the present invention provides a flush toilet designed to be flushed using flush water to discharge waste. The flush toilet comprises: a toilet main unit comprising a bowl portion for receiving waste, and a discharge trap pipe extending from a bottom end of the bowl portion; and a discharge conduit communicated with the discharge trap pipe, wherein the discharge conduit comprises: an upstream discharge conduit section; a flow

2

dividing section provided on a downstream side of the upstream discharge conduit section; a downstream discharge conduit section provided on a downstream side of the flow dividing section; and a delaying flow passage branched from the flow dividing section; wherein: the flow dividing section of the discharge conduit has a guide portion configured to guide relatively low-speed flush water supplied from the discharge trap pipe along the guide portion to the delaying flow passage, and to enable relatively high-speed flush water supplied from the discharge trap pipe to flow to the downstream discharge conduit section so as not to guide the relatively high-speed flush water along the guide portion to the delaying flow passage; and the delaying flow passage of the discharge conduit is configured such that flush water having flowed into the delaying flow passage along the guide portion of the flow dividing section is enabled to merge with a flush water flow reaching the flow dividing section at a timing after the inflow of the flush water to the delaying flow passage.

In the flush toilet of the present invention having the above feature, during toilet flushing, the guide portion of the flow dividing section guide relatively low-speed flush water flowing on a leading side of the waste (hereinafter referred to occasionally as "low-speed leading flush water" or "leading flush water") to the delaying flow passage, and the delaying flow passage enables flush water having flowed into the delaying flow passage to merge with a flow of the relatively high-speed flush water for washing down or convey the waste (hereinafter referred to occasionally as "high-speed waste conveyance flow" or "waste conveyance flow"), which reaches the flow dividing section at a timing after the inflow of the flush water to the delaying flow passage. This makes it possible to increase the volume of the waste conveyance flow to thereby improve waste conveyance capability (capability of conveying waste).

Further, in the flush toilet of the present invention, it is possible to enable the high-speed waste conveyance flow to flow to the downstream discharge conduit section so as not to guide the waste conveyance flow along the guide portion to the delaying flow passage. This can make it less likely for the waste conveyance flow to flow into the delaying flow passage, while selectively enabling the low-speed leading flush water to flow into the delaying flow passage.

Preferably, in the flush toilet of the present invention, the discharge trap pipe comprises an inlet path connected to the bottom of the bowl portion, a rise path extending obliquely upwardly from a downstream end of the inlet path, and a fall path descending from a downstream end of the rise path, and the flow dividing section of the discharge conduit has a downward flow passage extending in an upward-downward direction, wherein the guide portion of the flow dividing section is formed on the side of the rise path of the discharge trap pipe from the downward flow passage of the flow dividing section, and between the downward flow passage and the delaying flow passage.

According to this feature, during toilet flushing, the low-speed leading flush water flows down through a specific part of the downward flow passage on the side of the rise path of the discharge trap pipe, because the momentum of the low-speed leading flush water is relatively weak. On the other hand, during toilet flushing, when the high-speed waste conveyance flow flows from the rise path of the discharge trap pipe into the fall path of the discharge trap pipe and then into the downward flow passage of the flow dividing section, the high-speed waste conveyance flow flows down through the remaining part of the downward flow passage on a side opposite to the rise path of the

discharge trap pipe, because the momentum of the high-speed waste conveyance flow is relatively strong. This can make it less likely for the waste conveyance flow to flow into the delaying flow passage, while selectively enabling the low-speed leading flush water to flow into the delaying flow passage. This makes it possible to more efficiently enable the low-speed leading flush water to flow into the delaying flow passage and then merge with the waste conveyance flow.

Preferably, in the above flush toilet, the guide portion of the flow dividing section extends obliquely downwardly to form an acute angle with respect to a vertical line.

According to this feature, as compared to case where the guide portion of the flow dividing section forms an angle of 90 degrees or more with respect to the vertical line, a change in direction between the guide portion of the flow dividing section and the downward flow passage is reduced. This can make it less likely for the leading flush water to separate from the guide portion. This makes it possible to more efficiently guide the leading flush water to the delaying flow passage.

Preferably, in the above flush toilet, the guide portion of the flow dividing section is formed on a peripheral wall defining the downward flow passage, on the side of the rise path of the discharge trap pipe, and forms a cutout portion on the peripheral wall on a side opposite to the rise path.

According to this feature, the guide portion of the flow dividing section is formed on a peripheral wall defining the downward flow passage, on the side of the rise path of the discharge trap pipe, and forms a cutout portion on the peripheral wall on a side opposite to the rise path. Thus, it becomes possible to enable the high-speed waste conveyance flow to pass through the cutout-like portion so as to suppress the high-speed waste conveyance flow from flowing into the delaying flow passage along the guide portion.

Preferably, in the above flush toilet, a connection portion between a peripheral wall defining the downward flow passage and the guide portion of the flow dividing section is formed to have a curved surface.

According to this feature, the connection portion between the peripheral wall defining the downward flow passage and the guide portion of the flow dividing section is formed to have a curved surface, so that it is possible to make it less likely for a flow of the leading flush water to separate from the connection portion between the peripheral wall and the guide portion. This make it possible to further increase the volume of flush water to be enabled to flow into the delaying flow passage, i.e., further increase the volume of flush water to be enabled to merge with the waste conveyance flow.

Preferably, in the above flush toilet, a bottom wall of the delaying flow passage is formed so as to protrude inside the flow dividing section to a position below and opposed to the guide portion of the flow dividing section.

According to this feature, flush water separating and dropping from the guide portion of the flow dividing section can be received and introduced into the delaying flow passage by the bottom wall. This make it possible to further increase the volume of flush water to be enabled to flow into the delaying flow passage, i.e., further increase the volume of flush water to be enabled to merge with the waste conveyance flow.

Preferably, in the above flush toilet, an edge of the bottom wall of the delaying flow passage is located outward of the downward flow passage, in top view.

According to this feature, it is possible to suppress a situation where the bottom wall of the delaying flow passage causes the high-speed waste conveyance flow being flowing down through the downward flow passage of the flow

dividing section to undesirably flow into the delaying flow passage. This makes it possible to suppress a decrease in kinetic energy of the waste conveyance flow.

Preferably, in the flush toilet, the downward flow passage of the flow dividing section is formed to have an introduction surface extending approximately vertically from an upper end of the downward flow passage to an upper end of the guide portion.

According to this feature, the introduction surface extends approximately vertically from the upper end of the downward flow passage to the upper end of the guide portion, so that it is possible to guide the low-speed leading flush water to the guide portion along the introduction surface. This makes it possible to further increase the volume of the low-speed leading flush water which flows into the delaying flow passage along the guide portion.

Preferably, in the flush toilet of the present invention, the discharge conduit is a resin member which is a separate component from the toilet main unit.

According to this feature, the discharge conduit is a resin member which is a separate component from the toilet main unit, so that it becomes possible to easily perform fine adjustment of the position of the discharge conduit depending on the position of the downstream building sewer pipe.

Preferably, in the above flush toilet, a peripheral wall defining the downward flow passage of the flow dividing section is formed to have an introduction surface extending approximately vertically from an upper end of the downward flow passage to an upper end of the guide portion, and an inner peripheral surface of an outlet of the discharge trap pipe is formed so as to be approximately flush with the introduction surface of the flow dividing section of the discharge conduit.

According to this feature, the inner peripheral surface of the outlet of the discharge trap pipe is formed so as to be approximately flush with the introduction surface of the flow dividing section of the discharge conduit. Thus, even in the case where the discharge conduit and the discharge trap pipe are formed, respectively, as separate members, it is possible to reliably enable to the low-speed leading flush water to flow along the introduction surface. This makes it possible to further increase the volume of the low-speed leading flush water which flows into the delaying flow passage via the introduction surface and the guide portion.

Preferably, in the flush toilet of the present invention, the flow dividing section of the discharge conduit forms a transverse flow passage extending in a transverse direction, and wherein the guide portion of the flow dividing section is formed between the transverse flow passage of the flow dividing section and the delaying flow passage extending laterally from the transverse flow passage.

According to this feature, the waste conveyance flow has a relatively high flow rate, so that it is less likely to spread laterally in the transverse flow passage, i.e., tends to flow straight through the transverse flow passage. On the other hand, the leading flush water has a relatively low flow rate, so that it is more likely to spread laterally in the transverse flow passage. Thus, in the flow dividing section, the transverse flow passage can make it less likely for the waste conveyance flow to flow into the delaying flow passage, and the guide portion can efficiently selectively enable the leading flush water to flow into the delaying flow passage extending laterally from the transverse flow passage.

Preferably, in the above flush toilet, a connection portion between a peripheral wall defining the transverse flow passage and the guide portion of the flow dividing section is formed to have a curved surface.

According to this feature, the connection portion between the peripheral wall defining the transverse flow passage and the guide portion of the flow dividing section is formed to have a curved surface, so that it is possible to make it less likely for a flow of the leading flush water to separate from the connection portion between the peripheral wall defining the transverse flow passage and the guide portion. This make it possible to further increase the volume of flush water to be enabled to flow into the delaying flow passage, i.e., further increase the volume of flush water to be enabled to merge with the waste conveyance flow.

Preferably, in the above flush toilet, a downstream surface of the delaying flow passage is formed so as to protrude inside the flow dividing section to a position downstream of and opposed to the guide portion of the flow dividing section.

According to this feature, flush water separating from the guide portion of the flow dividing section and flowing toward a downstream side can be received and introduced into the delaying flow passage by the downstream surface of the delaying flow passage. This make it possible to further increase the volume of flush water to be enabled to flow into the delaying flow passage, i.e., further increase the volume of flush water to be enabled to merge with the waste conveyance flow.

Preferably, in the above flush toilet, an edge of the downstream surface of the delaying flow passage is located outward of the transverse flow passage, in side view as viewed from an upstream end of the transverse flow passage.

According to this feature, it is possible to suppress a situation where the downstream surface of the delaying flow passage causes the high-speed waste conveyance flow being flowing toward the downstream side through the transverse flow passage of the flow dividing section to undesirably flow into the delaying flow passage. This makes it possible to suppress a decrease in kinetic energy of the waste conveyance flow.

Preferably, in the above flush toilet, the discharge conduit is a resin member which is a separate component from the discharge trap pipe.

According to this feature, the discharge conduit is a resin member which is a separate component from the discharge trap pipe, so that it becomes possible to easily perform fine adjustment of the position of the discharge conduit depending on the position of the downstream building sewer pipe.

Advantageous Effects of Invention

The flush toilet of the present invention is capable of increasing the volume of the waste conveyance flow, even when the volume of flush water for toilet flushing is reduced in order to cope with demand for water-saving, thereby improving a waste conveyance capability.

BRIEF DESCRIPTION OF DRAWINGS

FIG. 1A is a vertical sectional view depicting a flush toilet according to a first embodiment of the present invention, wherein a state of leading flush water flowing on a leading side of waste, is indicated;

FIG. 1B is a vertical sectional view depicting the flush toilet according to the first embodiment, wherein a state of waste conveyance flow flowing on a trailing side of waste to wash down or convey the waste, is indicated;

FIG. 2 is a sectional view taken along the line II-II in FIG. 1A;

FIG. 3 is an enlarged perspective view depicting an internal structure of a discharge socket in the flush toilet according to the first embodiment depicted in FIG. 1A, wherein a vicinity of a flow dividing section of the discharge socket is partially cut away;

FIG. 4 is a top view depicting the discharge socket of the flush toilet according to the first embodiment;

FIG. 5 is a sectional view taken along the line V-V in FIG. 4;

FIG. 6 is a sectional view depicting the discharge socket of the flush toilet according to the first embodiment, taken along the line VI-VI in FIG. 5;

FIG. 7 is a top view depicting a discharge socket in a first modification of the flush toilet according to the first embodiment, wherein a delaying flow passage of the discharge socket in the flush toilet according to the first embodiment is modified;

FIG. 8 is a sectional view taken along the line VIII-VIII in FIG. 7;

FIG. 9 is a sectional view depicting the discharge socket in the first modification of the flush toilet according to the first embodiment, taken along the line IX-IX in FIG. 8;

FIG. 10 is a horizontal sectional view depicting an internal structure of a discharge socket in a second modification of the flush toilet according to the first embodiment, wherein the delaying flow passage of the discharge socket in the flush toilet according to the first embodiment is modified;

FIG. 11 is a sectional view depicting a third modification of the flush toilet according to the first embodiment, wherein the discharge socket and the toilet main unit in the flush toilet according to the first embodiment are integrally formed;

FIG. 12 is a side view depicting a discharge socket in a flush toilet according to a second embodiment of the present invention, wherein an internal passage of the discharge socket is indicated;

FIG. 13 is a sectional view taken along the line XIII-XIII in FIG. 12;

FIG. 14 is a sectional view taken along the line XIV-XIV in FIG. 12;

FIG. 15 is an enlarged perspective view depicting an internal structure of a discharge socket in a flush toilet according to a third embodiment of the present invention, wherein a vicinity of a flow dividing section of the discharge socket is partially cut away;

FIG. 16 is a vertical central sectional view depicting an internal structure of the discharge socket in the flush toilet according to the third embodiment;

FIG. 17 is a sectional view depicting the discharge socket of the flush toilet according to the third embodiment, taken along the line XVII-XVII in FIG. 16;

FIG. 18A is a sectional view depicting a first type of flush toilet in which a flow dividing section and a delaying flow passage of the discharge socket in the flush toilet according to at least one of the embodiments of the present invention are suitably usable, wherein the first type of flush toilet comprises a discharge trap pipe opened to face a floor, and a discharge socket to be connected to a building sewer pipe extending from a building wall;

FIG. 18B is a sectional view depicting a second type of flush toilet in which a flow dividing section and a delaying flow passage of the discharge socket in the flush toilet according to at least one of the embodiments of the present invention are suitably usable, wherein the second type of flush toilet comprises a discharge trap pipe opened to face a building wall, and a discharge socket to be connected to a building sewer pipe extending from the building wall; and

FIG. 18C is a sectional view depicting a third type of flush toilet in which a flow dividing section and a delaying flow passage of the discharge socket in the flush toilet according to at least one of the embodiments of the present invention are suitably usable, wherein the third type of flush toilet comprises a discharge trap pipe opened to face a building wall, and a discharge socket to be connected to a building sewer pipe extending from a floor

DESCRIPTION OF EMBODIMENTS

With reference to the accompanying drawings, a flush toilet according to a first embodiment of the present invention will now be described.

First of all, a flush toilet according to a first embodiment of the present invention will be described with reference to FIG. 1A and FIG. 2. FIG. 1A is a vertical sectional view depicting the flush toilet according to the first embodiment, wherein a state of leading flush water, i.e., flush water flowing on a leading side of waste, is indicated, and FIG. 2 is a sectional view taken along the line II-II in FIG. 1A.

As depicted in FIG. 1A, the flush toilet 1 comprises a toilet main unit 2 which has: a bowl portion 4 formed on a front side of an upper end thereof; a water conducting passage 6 on a rear side of the upper end; and a discharge trap pipe 8 formed beneath the water conducting passage 6 and the bowl portion 4 to extend from a bottom end of the bowl portion 4. The bowl portion 4 is formed in a bowl-like shape, and configured to receive waste therein. The flush toilet 1 is a water-saving wash-down type flush toilet designed to perform toilet flushing, for example, using 3.8 to 6-liter flush water.

Although the flush toilet 1 according to the first embodiment will be described based on an example where the present invention is applied to a floor-mounted wash-down type flush toilet, it is to be understood that the present invention is also applicable to any other suitable type of flush toilet, such as a wall-hung flush toilet or a siphon-type flush toilet configured to generate siphonage.

It should be noted that any embodiment of the present invention will be described based on the following assumption: an upper side and a lower side of the drawing sheet of FIG. 1A are defined, respectively, as a front side and a rear side of the toilet main unit 2, and a right side and a left side when viewing the toilet main unit 2 rearwardly from the front side thereof are defined, respectively, as a right side and a left side of the toilet main unit 2.

The bowl portion 4 of the toilet main unit 2 has an overhang-shaped rim 10 formed on an inner side of an upper edge region thereof, and a rim spout port 12 opened in a part of the rim 10 to spout flush water supplied from the water conducting passage 6, wherein the bowl portion 4 is configured to be cleaned or flushed with flush water swirlingly flowing downwardly after being spouted from the rim spout port 12.

The bowl portion 4 has a lower region formed as a water pooling region 14, wherein an accumulated water surface W_0 of pooled water is indicated by one-dot chain line. The discharge trap pipe 8 comprises an inlet path 8a connected to the bottom end of the bowl portion 4, a rise path 8b extending obliquely upwardly and rearwardly from a downstream end of the inlet path 8a, and a fall path 8c descending from a downstream end of the rise path 8b. The bowl portion 4 and the discharge trap pipe 8 are made of a ceramic material, and integrally molded with the toilet main unit 2. The inlet path 8a forms an inlet 8f of the discharge trap pipe 8.

The flush toilet 1 further comprises a flush water tank unit 18 provided on an upper side of the water conducting passage 6 of the toilet main unit 2 and configured to store therein flush water to be supplied to the toilet main unit 2. The flush water tank unit 18 comprises a flush water tank 20 storing therein flush water. This flush water tank 20 has a bottom wall formed with a discharge port 20a selectively communicable with the water conducting passage 6 of the toilet main unit 2 so as to discharge flush water stored in the flush water tank 20.

As depicted in FIG. 2, the toilet main unit 2 further comprises a skirt portion 9 provided to cover the bowl portion 4 and the discharge trap pipe 8 from a lateral side thereof. The skirt portion 9 is an exterior wall formed around the entire outer periphery of the toilet main unit 2. The skirt portion 9 is formed to extend from an upper end of the toilet main unit 2 to a floor F. Thus, the skirt portion 9 covers an outer side of the bowl portion 4, the discharge trap pipe 8 and an aftermentioned discharge socket 16.

In top plan view, an inward region of the skirt portion 9 comprises: a central region D extending in a forward-rearward (longitudinal) direction (a direction connecting the inlet 8f and an outlet 8d of the discharge trap pipe 8) as a region on an inner side of a width of the discharge trap pipe 8 in a rightward-leftward (lateral) direction (a direction orthogonal to the direction connecting the inlet 8f and the outlet 8d of the discharge trap pipe 8); and a lateral region E on both sides of the central region D. The central region D is a rectangular parallelepiped-shaped spatial region extending inside the skirt portion 9 from the bottom end to the upper end of the toilet main unit 2 with a width approximately equal to that of the discharge trap pipe 8. More specifically, the central region D is a region surrounded by the dotted lines G1, G2, and front and rear ends of the skirt portion 9, in top plan view. The lateral region E consists of two spatial regions each extending inside the skirt portion 9 from the bottom end to the upper end of the toilet main unit 2 on a respective one of the right and left sides of the central region D. More specifically, the lateral region E consists of a first side region surrounded by the dotted line G1 and part of the skirt portion 9 outside the dotted line G1, and a second side region surrounded by the dotted line G2 and part of the skirt portion 9 outside the dotted line G2, in top plan view.

With reference to FIGS. 3 to 6, a configuration of a discharge socket (a discharge device) 16 of the flush toilet 1 according to the first embodiment will be described in detail below. FIG. 3 is an enlarged perspective view depicting an internal structure of the discharge socket in the flush toilet according to the first embodiment depicted in FIG. 1A, wherein a vicinity of a flow dividing section of the discharge socket is partially cut away, and FIG. 4 is a top view depicting the discharge socket of the flush toilet according to the first embodiment. FIG. 5 is a sectional view taken along the line V-V in FIG. 4, and FIG. 6 is a sectional view depicting the discharge socket of the flush toilet according to the first embodiment, taken along the line VI-VI in FIG. 5.

The flush toilet 1 further comprises a discharge socket 16 which is a drain duct communicated with the discharge trap pipe 8 and configured to discharge waste to a building sewer pipe 22 on a downstream side thereof.

The discharge socket 16 comprises an upstream discharge conduit section 24, a flow dividing section 26, a delaying flow passage 28, and a downstream discharge conduit section 30, which are arranged approximately in this order in a direction from an upstream end to a downstream end thereof.

The discharge socket 16 is a resin member which is a separate component from the toilet main unit 2.

The upstream discharge conduit section 24 has an upstream end connected to the outlet 8d of the discharge trap pipe 8 (i.e., outlet 8d of the fall path 8c), and extends approximately parallel to the outlet 8d and vertically downwardly. The upstream discharge conduit section 24 extends from a position outside and above the outlet 8d of the fall path 8c to a position adjacent to and below the outlet 8d.

The downstream discharge conduit section 30 is provided on a downstream side of the flow dividing section 26. The downstream discharge conduit section 30 forms a transverse flow passage which extends linearly in a transverse direction to reach a position corresponding to the building sewer pipe 22. The downstream discharge conduit section 30 has a downstream end connected to the building sewer pipe 22 which is disposed below the floor F on which the toilet main unit 2 is placed.

The flow dividing section 26 is provided on a downstream side of the upstream discharge conduit section 24. The flow dividing section 26 is connected to the upstream discharge conduit section 24 and to the downstream discharge conduit section 30. The flow dividing section 26 is a linear passage extending vertically between the upstream discharge conduit section 24 and the downstream discharge conduit section 30. In FIG. 5, the flow dividing section 26 is indicated by the dotted line. The flow dividing section 26 has a guide portion 32 configured to guide therealong at least part of relatively low-speed flush water (low-speed leading flush water) supplied from the discharge trap pipe 8 so as to flow into the delaying flow passage 28. The flow dividing section 26 has a downward flow passage (downward flow passage region) 34 extending from an upper end to a lower end of the flow dividing section 26 in an upward-downward direction, inside the guide portion 32. In FIG. 5, the downward flow passage 34 is indicated by the one-dot chain line.

The guide portion 32 of the flow dividing section 26 is formed on the side of the rise path 8b of the discharge trap pipe 8 from a peripheral wall 34a defining the downward flow passage 34 of the flow dividing section 26, and between the downward flow passage 34 of the flow dividing section 26 and the delaying flow passage 28. In other words, the guide portion 32 is disposed forward of the downward flow passage 34. The guide portion 32 is formed to hang down such that it extends obliquely downwardly from an upper end thereof and has a lower end expanding toward an inside of the delaying flow passage 28. The guide portion 32 forms an acute angle α_1 with respect to a vertical line Z. The angle α_1 may be set in the range of 5 to 60 degrees, preferably in the range of 5 to 45 degrees, more preferably to 30 degrees. Between the lower end of the guide portion 32 and a bottom wall surface 50 of the delaying flow passage 28, an inflow opening is formed.

As depicted in FIG. 4, the guide portion 32 is formed on the peripheral wall 34a defining the downward flow passage 34, on the side of the rise path 8b of the discharge trap pipe 8, and forms a cutout-like portion (cutout portion) 36 on the peripheral wall 34a on a side opposite to the rise path 8b. The cutout-like portion 36 provides a cutoff space in the downward flow passage 34 between one side end and the other side end of the guide portion 32. The guide portion 32 is formed along approximately one-half of the entire circumference of the peripheral wall 34a. In FIG. 4, the cutout-like space 36 is generally indicated by the two-dot chain line. The guide portion 32 is not formed in the cutout space along the cutout-like portion 36, so that a flow of relatively high-speed flush water for conveying waste (high-

speed waste conveyance flow) is suppressed from colliding with the guide portion 32, and thus flows down through the cutout space along the cutout-like portion 36 while maintaining relatively strong momentum.

As depicted in FIGS. 3 and 5, a connection portion 38 between the peripheral wall 34a and the guide portion 32 of the flow dividing section 26 is formed to have a smoothly curved surface. The peripheral wall 34a of the flow dividing section 26 is formed to have an introduction surface 34b which extends approximately vertically to the upper end of the guide portion 32. An inner peripheral surface 8e of the outlet 8d of the discharge trap pipe 8 is formed so as to be approximately flush with the introduction surface 34b of the flow dividing section 26 of the discharge socket 16 (see FIG. 1A).

As depicted in FIG. 6, the delaying flow passage 28 forms a flow passage branched from the flow dividing section 26. The delaying flow passage 28 forms a flow passage in the lateral region E. The delaying flow passage 28 is configured such that flush water flowing on a leading side of the waste and having flowed thereto from the flow dividing section 26 is enabled to merge with a flush water flow reaching the flow dividing section 26 at a timing after the inflow of the flush water to the delaying flow passage 28. The delaying flow passage 28 is disposed to extend from the guide portion 32 in a transverse direction. The delaying flow passage 28 is formed bilaterally symmetrically with respect to a longitudinal axis of the toilet main unit 2.

The delaying flow passage 28 comprises a connection zone 46 connecting with the flow dividing section 26, and an extended flow passage 48 extending from the connection zone 46 toward the lateral region E.

The connection zone 46 is connected to a specific part of the flow dividing section 26 on the side of the rise path 8b. The connection zone 46 has an entrance 40 for accepting flush water guided along the guide portion 32. This entrance 40 also functions as an exit 44 for enabling flush water having flowed into the connection zone 46 to flow out therefrom. The connection zone 46 further functions as a reservoir chamber for enabling flush water having flowed thereto from the entrance 40 to flow thereinside so as to temporarily stay therein until it flows out from the exit 44. The entrance 40 of the connection zone 46 is located below and outside the guide portion 32. The entrance 40 is formed as an opening including about one-half of the entire circumference of the flow dividing section 26 on the side of the rise path 8b. That is, the delaying flow passage 28 is a reservoir-type delaying flow passage in which a single opening is used as both of the entrance 40 and the exit 44, and flush water temporarily stays therein while flowing thereinside. Further, the connection zone 46 forms a bent flow passage for changing a flow direction of flush water having flowed thereto from the flow dividing section 26, toward the lateral region E on a lateral side thereof. The connection zone 46 forming the bent flow passage makes it possible to reduce the flow speed of flush water flowing thereinside. Thus, by enabling flush water to flow inside the connection zone 46, it becomes possible to delay a timing at which this flush water flows through the discharge socket 16, with respect to an initial state. Based on this mechanism, the delaying flow passage 28 makes it possible for flush water having flowed thereto along the guide portion 32 of the flow dividing section 26 to merge with a flush water flow reaching the flow dividing section 26 at a timing after the inflow of the flush water to the delaying flow passage 28, in a delayed manner.

11

The extended flow passage 48 is provided in each of the first and second side regions of the lateral region E on both sides of the central region D. Alternatively, the extended flow passage 48 may be provided in only one of the first and second side regions of the lateral region E on both sides of the central region D. Further, although the extended flow passage 48 in the first embodiment is provided only in the lateral region E, the extended flow passage 48 may be provided in each of the central region D and the lateral region E. The extended flow passage 48 extends in the direction connecting the inlet 8f and the outlet 8d of the discharge trap pipe 8, i.e., the forward-rearward (longitudinal) direction of the toilet main unit 2. In side view, the extended flow passage 48 extends from a position beneath the fall path 8c of the discharge trap pipe 8 to a position where it partially overlaps the discharge trap pipe 8. The extended flow passage 48 extends the delaying flow passage 28 to an inside of the lateral region E. The extended flow passage 48 expands the delaying flow passage 28 to a wider region in the lateral region E to increase a bottom surface area of the delaying flow passage 28. In this embodiment, the bottom surface area of the delaying flow passage 28 is increased by the extended flow passage 48, as mentioned above. Thus, even in a situation where the flow speed of inflowing flush water is fairly low, it is possible to make it easier to enable the flush water to flow into a wider region of the delaying flow passage 28, and thus make it easier to enable the flush water to flow into the delaying flow passage 28 in a larger volume, as compared to case where the delaying flow passage 28 has a smaller bottom surface area. Thus, by forming the delaying flow passage 28 in the lateral region E to increase the bottom surface area of the delaying flow passage 28 in the lateral region E, it becomes possible to more reliably increase the volume of flush water flowing through the delaying flow passage, irrespective of the flow speed of inflowing flush water. The extended flow passage 48 additionally functions as a reservoir chamber for allowing flush water to temporarily stay therein. The extended flow passage 48 is configured to cause flush water having flowed thereto from the connection zone 46 to flow therethrough while turning back toward the connection zone 46, thereby reducing the flow speed of flush water having flowed thereto.

Further, as depicted in FIGS. 5 and 6, the delaying flow passage 28 is formed such that the bottom wall surface 50 thereof protrudes inside the flow dividing section 26 to reach a position below and opposed to the guide portion 32 of the flow dividing section 26. In top view, an edge 50a of the bottom wall surface 50 of the delaying flow passage 28 is located outward of an outer edge of the downward flow passage 35. The delaying flow passage 28 is formed such that the bottom wall surface 50 in the connection zone 46 and the extended flow passage 48 slightly inclines downwardly toward the entrance 40. This makes it possible to reduce the flow speed of inflowing flush water, and discharge water remaining in the delaying flow passage 28, toward the entrance 40.

With reference to FIGS. 1A, 1B and 6, an operation (function) of the flush toilet according to the first embodiment will be described below.

Specifically, a state when draining is performed along with toilet flushing in the flush toilet according to the first embodiment will be described with reference to FIGS. 1A, 1B and 6. In FIGS. 1A, 1B and 6, a flow of leading flush water, i.e., relatively low-speed flush water flowing on a leading side of waste C, is indicated by the arrowed lines A (A0 to A6), and a waste conveyance flow, i.e., flush water

12

mainly flowing on a trailing side of the waste C to wash down or convey the waste C, is indicated by the arrowed lines B (B0 to B4). As used herein, the term "leading side of the waste C" means a forward side preceding the waste C on a flow passage along which the waste C is flowing. Further, the term "trailing side of the waste C" means a rearward side following the waste C on the flow passage along which the waste C is flowing.

As depicted in FIGS. 1A, 1B and 6, after a user uses the flush toilet 1, the discharge port 20a of the flush water tank 20 of the flush water tank unit 18 is opened, and thus flush water is discharged from the discharge port 20a to the water conducting passage 6 of the toilet main unit 2. Then, the flush water in the water conducting passage 6 is spouted from the rim spout port 12 of the flush toilet 1 to perform flushing of the toilet main unit 2. According to a water flow action caused by drop of flush water from the water conducting passage 6 to the water pooling region 14, flush water containing the waste C in the water pooling region 14 is pushed from the inlet path 8a to the rise path 8b and the fall path 8c of the discharge trap pipe 8 and then sent to the outlet 8d the discharge trap pipe 8.

Firstly, a state in which relatively low-speed flush water is flowing on the leading side of the waste C will be described.

As depicted in FIG. 1A, at a start of toilet flushing, relatively low-speed flush water A flows on the leading side of the waste C, as indicated by the arrowed line A0. The leading flush water A flowing on the leading side of the waste C also has a relatively small volume.

As depicted in FIG. 1A, at the start of toilet flushing, the leading flush water A gradually flows out from the rise path 8b to the side of the fall path 8c. The relatively low-speed leading flush water A has weak momentum, and thus flows down along part of the inner peripheral surface 8e of the fall path 8c on the side of the rise path 8b, as indicated by the arrowed line A1. Further, the leading flush water A flows down from the inner peripheral surface 8e into the discharge socket 16 smoothly along the introduction surface 34b of the flow dividing section 26, and is then guided along the guide portion 32 so as to flow from the introduction surface 34b toward the delaying flow passage 28, as indicated by the arrowed line A2. The leading flush water A is drawn to the guide portion 32 by the Coanda effect, so that a flow direction thereof is changed to a direction along which the guide portion 32 extends. In this way, at least part of the leading flush water A flows into the entrance 40 of the connection zone 46 of the delaying flow passage 28, as indicated by the arrowed line A3. The leading flush water A having flowed into the connection zone 46 flows from the connection zone 46 toward the extended flow passage 48, as indicated by the arrowed lines A4 in FIG. 9. The flow direction of the leading flush water A is changed within the connection zone 46, so that the flow speed of the leading flush water A is reduced as compared to that at a timing of flowing through the connection zone 46 and the extended flow passage 48, the leading flush water A is delayed with respect to a flow of flush water flowing through the downward flow passage 34 as a main flow passage. The leading flush water A gently flows in such a manner as to be temporarily held in the connection zone 46 and the extended flow passage 48, and then returns to the main stream. When the volume of flush water flowing into the entrance 40 of the connection zone 46 becomes small or zero after elapse of a given time from the start of toilet flushing, the leading flush water A in the connection zone 46 and the extended flow

13

passage 48 flows toward the exit 44 and then flows out toward the downward flow passage 34 through the exit 44, as indicated by the arrowed line A5 in FIG. 1B.

As used herein, the term "Coanda effect" means a phenomenon that a jet flow is bent along a solid wall. For example, there is a phenomenon that, when a finger is moved close to water from a faucet, a flow of the water is bent toward the finger. This phenomenon is also caused by the Coanda effect.

Secondly, a waste conveyance flow for washing down waste will be described.

As depicted in FIG. 1A, at a start of toilet flushing, according to a water flow action caused by drop of flush water from the water conducting passage 6 to the water pooling region 14, a waste conveyance flow B for strongly washing down waste is formed.

The waste conveyance flow B acting to wash down the waste C flows around the waste C and mainly on the trailing side of the waste C, as indicated by the arrowed line B0. The waste conveyance flow B is formed mainly of trailing flush water flowing on the trailing side of the waste C. The waste conveyance flow B has a relatively high flow speed and a relatively large flow volume. The waste conveyance flow B acts to push the waste C mainly from the trailing side thereof so as to wash down the waste C. The inventor of the present invention found that a force of the waste conveyance flow B acting to wash down the waste C and kinetic energy of the waste conveyance flow B can be further improved by increasing the volume of the waste conveyance flow B.

As depicted in FIG. 1B, because the waste C and the waste conveyance flow B have a relatively high flow speed, a main stream of the waste conveyance flow B with the waste C flows down along part of a peripheral wall of the fall path 8c on the side opposite to the rise path 8b, as indicated by the arrowed line B1. Then, the main stream of the waste conveyance flow B with the waste C passes by the cutout-like portion 36 of the peripheral wall 34a of the downward flow passage 34, on the side opposite to the rise path 8b, as indicated by the arrowed line B2. The main stream of the waste conveyance flow B with the waste C further flows down through the downward flow passage 34 as the main flow passage as indicated by the arrowed line B3, so that it is suppressed from colliding with the bottom wall of the delaying flow passage 28 and flowing into the delaying flow passage 28.

As regards the leading flush water A having a relatively low flow speed, a relatively large proportion by volume of leading flush water A flowing from the discharge trap pipe 8 is guided to the delaying flow passage 28 along the guide portion 32. On the other hand, as regards the waste conveyance flow B having a relatively high flow speed, a relatively small proportion by volume of a waste conveyance flow B flowing from the discharge trap pipe 8 is guided to the delaying flow passage 28 along the guide portion 32, as indicated by the arrowed line B1. Thus, a rate of part of the leading flush water A to be guided to the delaying flow passage 28 along the guide portion 32 is greater than a rate of part of the waste conveyance flow B to be guided to the delaying flow passage 28 along the guide portion 32. In this case, the rate of the part of the waste conveyance flow B to be guided to the delaying flow passage 28 along the guide portion 32 is 0% or more.

The leading flush water A flowing out to the downward flow passage 34 through the exit 44 merges with the waste conveyance flow B, as indicated by the arrowed line A6. As mentioned above, the leading flush water A having flowed into the delaying flow passage 28 flows inside the delaying

14

flow passage 28 until it flows out toward the downward flow passage 34 through the exit 44. In this process, a given time has elapsed. Thus, the leading flush water A merges with the waste conveyance flow B reaching the downward flow passage 34 of the flow dividing section 26 at a timing after a given time has elapsed since the inflow of the leading flush water A to the delaying flow passage 28. That is, part of the leading flush water A having flowed into the delaying flow passage 28 is converted to the waste conveyance flow B.

This makes it possible to add the leading flush water A contributing less to conveyance of the waste C, to the waste conveyance flow B, and thus increase the volume of the waste conveyance flow B as indicated by the arrowed line B4, thereby improving a capability of conveying the waste C (waste conveyance capability). The arrowed line B4 indicates the improved waste conveyance flow B which is increased in terms of flow rate and/or volume based on merging of the leading flush water A and the waste conveyance flow B.

The improved waste conveyance flow B with the waste C flows toward the downstream side through the downstream discharge conduit section 30, and is finally discharged into the building sewer pipe 22.

Next, with reference to FIGS. 7 to 9, a first modification of the flush toilet according to the first embodiment will be described, wherein the delaying flow passage 28 of the discharge socket 16 in the flush toilet according to the first embodiment is modified.

In the first modification, the same element or component as that in the above first embodiment is assigned with the same reference numeral or sign, and its description will be omitted. In the first embodiment, the delaying flow passage 28 of the discharge socket 16 is a reservoir-type delaying flow passage in which a single opening is used as both of the entrance 40 and the exit 44, and flush water temporarily stays therein.

However, the first embodiment may be modified to employ a bypass-type delaying flow passage 128 in which the entrance 40 and the exit 44 are separately arranged to form a bypass flow passage for flush water, instead of the above reservoir-type delaying flow passage 28.

A discharge socket 16 in the first modification comprises an upstream discharge conduit section 24, a flow dividing section 26, a delaying flow passage 128, and a downstream discharge conduit section 130, which are arranged approximately in this order in a direction from an upstream end to a downstream end thereof.

The downstream discharge conduit section 130 is provided on a downstream side of the flow dividing section 26. The downstream discharge conduit section 130 forms a transverse flow passage which extends linearly in a transverse direction to reach a position of a building sewer pipe 22. The downstream discharge conduit section 130 has a downstream end connected to the building sewer pipe 22 which is disposed below the floor F on which a toilet main unit 2 is placed. The downstream discharge conduit section 130 has an opening formed in an upper wall of a downstream portion thereof and configured to accept flush water which flows down from an aforementioned exit 144.

As depicted in FIGS. 7 to 9, the delaying flow passage 128 forms a flow passage branched from the flow dividing section 26. The delaying flow passage 128 forms the flow passage in a lateral region E. The delaying flow passage 128 is configured such that leading flush water having flowed thereto from the flow dividing section 26 is enabled to merge with a flush water flow reaching the flow dividing section 26 at a timing after the inflow of the leading flush

15

water to the delaying flow passage 128. The delaying flow passage 128 is disposed to extend from a guide portion 32 in a forward transverse direction. The delaying flow passage 128 is formed bilaterally symmetrically with respect to a central axis in a forward-rearward direction of the toilet main unit 2.

The delaying flow passage 128 comprises a connection zone 146 connecting with the flow dividing section 26, and an extended flow passage 148 extending from the connection zone 146 toward the lateral region E.

The connection zone 146 is connected to a specific part of the flow dividing section 26 on the side of a rise path 8b of a discharge trap pipe 8. The connection zone 146 has an entrance 40 for accepting flush water guided along the guide portion 32. The connection zone 146 further functions as a reservoir chamber for enabling flush water having flowed thereinto from the entrance 40 to flow thereinside so as to temporarily stay therein until it flows out from the after-mentioned exit 144. The delaying flow passage 128 further comprises an exit 144 provided separately from the entrance 40 of the connection zone 146 and configured to allow flush water having flowed into the delaying flow passage 128 to flow out therefrom. The exit 144 forms an exit of the extended flow passage 148. Thus, the connection zone 146 and the extended flow passage 148 of the delaying flow passage 128 form a bypass flow passage extending from the entrance 40 to the exit 144.

The connection zone 146 forms a bent flow passage for changing a flow direction of flush water having flowed thereinto from the flow dividing section 26, toward the lateral region E on a lateral side thereof. The connection zone 146 forming the bent flow passage makes it possible to reduce the flow speed of flush water flowing thereinside. Thus, by enabling flush water to flow inside the connection zone 146, it becomes possible to delay a timing at which this flush water flows through the discharge socket 16, with respect to an initial state.

The extended flow passage 148 comprises a first extended flow passage 148a provided in one of the first and second side regions of the lateral region E on both sides of a central region D, and a second extended flow passage 148b provided in the other side region of the lateral region E. As above, the extended flow passage 148 is provided in each of the first and second side regions of the lateral region E on both sides of the central region D. Alternatively, the extended flow passage 148 may be provided in only one of the first and second side regions of the lateral region E on both sides of the central region D. Further, although the extended flow passage 148 in the first embodiment is provided only in the lateral region E, the extended flow passage 148 may be provided in each of the central region D and the lateral region E. The extended flow passage 148 extends in a direction along the discharge trap pipe 8, i.e., a forward-rearward (longitudinal) direction of the toilet main unit 2. In side view, the extended flow passage 148 extends from a position beneath a fall path 8c of the discharge trap pipe 8 to a position where it partially overlaps the discharge trap pipe 8. The extended flow passage 148 extends the delaying flow passage 128 in the lateral region E. The extended flow passage 148 expands the delaying flow passage 128 to a wider region in the lateral region E to increase a bottom surface area of the delaying flow passage 128. The bottom surface area of the delaying flow passage 128 is increased by the extended flow passage 148, as mentioned above. Thus, even in a situation where the flow speed of inflowing flush water is fairly low, it is possible to make it easier to enable the flush water to flow into a wider region

16

of the delaying flow passage 128, and thus make it easier to enable the flush water to flow into the delaying flow passage 128 in a larger volume, as compared to case where the delaying flow passage 128 has a smaller bottom surface area. Thus, by forming the delaying flow passage 128 in the lateral region E to increase the bottom surface area of the delaying flow passage 128 in the lateral region E, it becomes possible to more reliably increase the volume of flush water flowing through the delaying flow passage, irrespective of the flow speed of inflowing flush water. The extended flow passage 148 additionally functions as a reservoir chamber for allowing flush water to temporarily stay therein. The extended flow passage 148 is configured to reduce the flow speed of flush water having flowed thereinto from the connection zone 146, during a course in which the flush water having flowed thereinto flows therethrough transversely with respect to a vertical direction.

The delaying flow passage 128 is formed such that a bottom wall surface 50 thereof in the connection zone 146 and the extended flow passage 148 slightly inclines downwardly toward the exit 144, respectively. This makes it possible to adequately reduce the flow speed of inflowing flush water, and discharge water remaining in the delaying flow passage 128, toward the exit 144.

The exit 144 is formed separately from the entrance 40, at a position different from that of the entrance 40. Specifically, the exit 144 is formed at a downstream end of the extended flow passage 148. The exit 144 comprises a first exit 144a forming an exit of the first extended flow passage 148a, and a second exit 144b forming an exit of the second extended flow passage 148b. The exit 144 is formed at a position above the downstream discharge conduit section 130 and above the building sewer pipe 22. The exit 144 is opened downwardly to enable flush water to flow down into the downstream discharge conduit section 130 and the building sewer pipe 22. Thus, the delaying flow passage 128 is a bypass-type delaying flow passage in which the entrance 40 and the exit 144 are separately arranged to form a bypass flow passage for flush water. Based on the above structure, the delaying flow passage 128 makes it possible to enable flush water having flowed therein along the guide portion 32 of the flow dividing section 26 to merge with a flush water flow reaching the flow dividing section 26 at a timing after the inflow of the flush water to the delaying flow passage 128, at a given position of the downstream discharge conduit section 130. The first extended flow passage 148a extending from the connection zone 146 to the first exit 144a and the second extended flow passage 148b extending from the connection zone 146 to the second exit 144b are formed independently of each other.

With reference to FIGS. 1A, 1B and 7 to 9, an operation (function) pertaining to the delaying flow passage in the first modification of the flush toilet according to the first embodiment will be described below.

Specifically, a state when draining is performed along with toilet flushing in the first modification of the flush toilet according to the first embodiment will be described with reference to FIGS. 1A, 1B, 8 and 9. In FIGS. 1A, 1B, 8 and 9, a flow of leading flush water, i.e., relatively low-speed flush water flowing on a leading side of waste C, is indicated by the arrowed lines A (A0 to A4, A7 and A8), and a waste conveyance flow, i.e., relatively high-speed flush water mainly flowing on a trailing side of the waste C to wash down or convey the waste C, is indicated by the arrowed lines B (B0 to B3, B5 and B6). In the following description about the operation in the first modification, the same element or component as that in the above first embodiment

is also assigned with the same reference numeral or sign, and its description will be omitted.

Firstly, a state in which relatively low-speed flush water is flowing on the leading side of the waste C will be described.

As depicted in FIG. 1A, at a start of toilet flushing, relatively low-speed flush water A flows on the leading side of the waste C, as indicated by the arrowed line A0.

As depicted in FIG. 1A, at the start of toilet flushing, the leading flush water A gradually flows out from the rise path 8b to the side of the fall path 8c. The relatively low-speed leading flush water A has weak momentum, and thus flows down along part of an inner peripheral surface 8e of the fall path 8c on the side of the rise path 8b, as indicated by the arrowed line A1. Further, the leading flush water A flows down from the inner peripheral surface 8e into the discharge socket 16 smoothly along an introduction surface 34b of the flow dividing section 26, and is then guided along the guide portion 32 so as to flow from the introduction surface 34b toward the delaying flow passage 128, as indicated by the arrowed line A2. The leading flush water A is drawn to the guide portion 32 by the Coanda effect, so that a flow direction thereof is changed to a direction along which the guide portion 32 extends. As depicted in FIG. 9, at least part of the leading flush water A flows into the entrance 40 of the delaying flow passage 128, as indicated by the arrowed lines A3. The leading flush water A having flowed into the connection zone 146 flows from the connection zone 146 toward the extended flow passage 148, as indicated by the arrowed lines A4. The flow direction of the leading flush water A is changed within the connection zone 146, so that the flow speed of the leading flush water A is reduced as compared to that at a timing of the inflow to the delaying flow passage 128.

The connection zone 146 and the extended flow passage 148 form a bypass flow passage. Thus, the leading flush water A flows through the extended flow passage 148 and turns toward the exit 144 of the extended flow passage 148, as depicted in the arrowed lines A7. As a result of flowing through the connection zone 146 and the extended flow passage 148, the leading flush water A is delayed with respect to a flow of flush water flowing through a downward flow passage 34 as a main flow passage. Then, the leading flush water A flows down from the exit 144, as indicated by the arrowed line A8 in FIG. 8, and flows down through the downstream discharge conduit section 130 and the building sewer pipe 22.

Secondly, a waste conveyance flow for washing down waste will be described.

As indicated by the arrowed line B0 in FIGS. 1A and 1B, a waste conveyance flow B acting to wash down the waste C flows around the waste C and mainly on the trailing side of the waste C. A main stream of the waste conveyance flow B with the waste C flows down along part of a peripheral wall of the fall path 8c on the side opposite to the rise path 8b, as indicated by the arrowed line B1. Then, the main stream of the waste conveyance flow B with the waste C passes by a cutout-like portion 36 of a peripheral wall 34a of the downward flow passage 34, as indicated by the arrowed line B2. The main stream of the waste conveyance flow B with the waste C further flows down through the downward flow passage 34 as indicated by the arrowed line B3, so that colliding with the bottom wall surface 50 of the delaying flow passage 128 and flowing into the delaying flow passage 128 can be suppressed.

As depicted in FIG. 8, the main stream of the waste conveyance flow B with the waste C flows through the

downstream discharge conduit section 130, as indicated by the arrowed line B5. The leading flush water A flowing out through the exit 144 merges with the main stream of the waste conveyance flow B with the waste C in a downstream portion of the downstream discharge conduit section 130, as indicated by the arrowed line A8. As mentioned above, the leading flush water A having flowed into the delaying flow passage 128 passes through the bypass flow passage comprising the connection zone 146 and the extended flow passage 148 and having a given distance, until it flows out toward the downstream discharge conduit section 130 through the exit 144. In this process, a given time has elapsed. Further, the leading flush water A passing through the bypass flow passage has a relatively low flow speed, and the waste conveyance flow B as a trailing flow has a relatively high flow speed. Thus, the leading flush water A having flowed into the delaying flow passage 128 merges with the waste conveyance flow B reaching the downward flow passage 34 of the flow dividing section 26 at a delayed timing after an elapse of a given time since the inflow of the leading flush water A to the delaying flow passage 128, at a position of the downstream portion of the downstream discharge conduit section 130. That is, part of the leading flush water A having flowed into the delaying flow passage 128 is converted to the waste conveyance flow B. This makes it possible to add the leading flush water A contributing less to conveyance of the waste C, to the waste conveyance flow B, and thus increase the volume of the waste conveyance flow B as indicated by the arrowed line B6, thereby improving a capability of conveying the waste C (waste conveyance capability). The arrowed line B6 indicates the improved waste conveyance flow B which is increased in terms of flow rate and/or volume based on merging of the leading flush water A and the waste conveyance flow B.

The waste C and the improved waste conveyance flow B further flow toward the downstream side through the downstream discharge conduit section 30, and is finally discharged into the building sewer pipe 22.

Next, with reference to FIG. 10, a second modification of the flush toilet according to the first embodiment will be described, wherein the delaying flow passage 28 of the discharge socket 16 in the flush toilet according to the first embodiment is modified. In the second modification, the same element or component as that in the above first embodiment is assigned with the same reference numeral or sign, and its description will be omitted. In the first embodiment, the delaying flow passage 28 of the discharge socket 16 is a reservoir-type delaying flow passage in which a single opening is used as both of the entrance 40 and the exit 44, and flush water temporarily stays therein.

However, the first embodiment may be modified to employ a bypass-type delaying flow passage 228 in which the entrance 40 and the exit 44 are separately arranged to form a bypass flow passage for flush water, instead of the above reservoir-type delaying flow passage 28.

A discharge socket 16 in the second modification comprises an upstream discharge conduit section 24, a flow dividing section 26, a delaying flow passage 228, and a downstream discharge conduit section 30, which are arranged approximately in this order in a direction from an upstream end to a downstream end thereof.

As depicted in FIG. 10, the delaying flow passage 228 forms a flow passage branched from the flow dividing section 26. The delaying flow passage 228 forms the flow passage in a lateral region E. The delaying flow passage 228 is configured such that leading flush water having flowed

thereinto from the flow dividing section 26 is enabled to merge with a flush water flow reaching the flow dividing section 26 at a timing after the inflow of the leading flush water to the delaying flow passage 228. The delaying flow passage 228 is disposed to extend from a guide portion 32 in a forward transverse direction. The delaying flow passage 228 is formed bilaterally symmetrically with respect to a longitudinal axis of a toilet main unit 2.

The delaying flow passage 228 comprises a connection zone 246 connecting with the flow dividing section 26, and an extended flow passage 248 extending from the connection zone 246 toward the lateral region E.

The connection zone 246 is connected to a specific part of the flow dividing section 26 on the side of a rise path 8b of a discharge trap pipe 8. The connection zone 246 has an entrance 40 for accepting flush water guided along the guide portion 32. The connection zone 246 further functions as a reservoir chamber for enabling flush water having flowed thereinto from the entrance 40 to flow thereinside so as to temporarily stay therein until it flows out from an aforementioned exit 244. The delaying flow passage 228 further comprises an exit 244 provided separately from the entrance 40 of the connection zone 246 and configured to allow flush water having flowed into the delaying flow passage 228 to flow out therethrough. The exit 244 forms an exit of the extended flow passage 248. Thus, the connection zone 246 and the extended flow passage 248 of the delaying flow passage 228 form a bypass flow passage extending from the entrance 40 to the exit 244.

The connection zone 246 forms a bent flow passage for changing a flow direction of flush water having flowed thereinto from the flow dividing section 26, toward the lateral region E on a lateral side thereof. The connection zone 246 forming the bent flow passage makes it possible to reduce the flow speed of flush water flowing thereinside. Thus, by enabling flush water to flow inside the connection zone 246, it becomes possible to delay a timing at which this flush water flows through the discharge socket 16, with respect to an initial state.

The extended flow passage 248 comprises a first extended flow passage 248a provided in one of the first and second side regions of the lateral region E on both sides of a central region D, and a second extended flow passage 248b provided in the other side region of the lateral region E. As above, the extended flow passage 248 is provided only in each of the first and second side regions of the lateral region E on both sides of the central region D. Alternatively, the extended flow passage 248 may be provided in only one of the first and second side regions of the lateral region E on both sides of the central region D. Further, although the extended flow passage 248 in the second modification is provided only in the lateral region E, the extended flow passage 248 may be provided in each of the central region D and the lateral region E. The extended flow passage 248 extends in a direction along the discharge trap pipe 8, i.e., a forward-rearward (longitudinal) direction of the toilet main unit 2. The extended flow passage 248 extends from the connection zone 246 toward a front end of the toilet main unit 2. Then, the extended flow passage 248 U-turns outwardly and extends rearwardly to a lateral side of the flow dividing section 26. In side view, the extended flow passage 248 extends from a position beneath a fall path 8c of the discharge trap pipe 8 to a position where it partially overlaps the discharge trap pipe 8. The extended flow passage 248 extends the delaying flow passage 228 in the lateral region E. The extended flow passage 248 expands the delaying flow passage 228 to a wider region in the lateral region E to

increase a bottom surface area of the delaying flow passage 228. The bottom surface area of the delaying flow passage 228 is increased by the extended flow passage 248, as mentioned above. Thus, even in a situation where the flow speed of inflowing flush water is fairly low, it is possible to make it easier to enable the flush water to flow into a wider region of the delaying flow passage 228, and thus make it easier to enable the flush water to flow into the delaying flow passage 228 in a larger volume, as compared to case where the delaying flow passage 228 has a smaller bottom surface area. Thus, by forming the delaying flow passage 228 in the lateral region E to increase the bottom surface area of the delaying flow passage 228 in the lateral region E, it becomes possible to more reliably increase the volume of flush water flowing through the delaying flow passage, irrespective of the flow speed of inflowing flush water. The extended flow passage 248 additionally functions as a reservoir chamber for allowing flush water to temporarily stay therein. The extended flow passage 248 is configured to reduce the flow speed of flush water having flowed thereinto from the connection zone 246, during a course in which the flush water having flowed thereinto flows therethrough transversely over a relatively long distance.

The delaying flow passage 228 is formed such that a bottom wall surface 50 thereof in the connection zone 246 and the extended flow passage 248 slightly inclines downwardly toward the exit 244, respectively. This makes it possible to reduce the flow speed of inflowing flush water, and discharge water remaining in the delaying flow passage 228, toward the exit 244.

The exit 244 is formed separately from the entrance 40, at a position different from that of the entrance 40. Specifically, the exit 244 is formed at a downstream end of the extended flow passage 248. The exit 244 comprises a first exit 244a forming an exit of the first extended flow passage 248a, and a second exit 244b forming an exit of the second extended flow passage 248b. The exit 244 is formed such that it is opened in a peripheral wall defining a downward flow passage 34 of the flow dividing section 26. Thus, the exit 244 is opened toward the flow dividing section 26 located upstream of a transverse flow passage of the downstream discharge conduit section 30. That is, the exit 244 is opened to enable flush water having flowed into the delaying flow passage 228 to flow out to an inside of the downward flow passage 34 of the flow dividing section 26. The exit 244 is formed at a position on a lateral side of the downward flow passage 34 and rearward of the entrance 40. Further, in top view, the exit 244 is located between an end of the downward flow passage 34 on a side opposite to the rise path 8b and both ends of the guide portion 32 on the side opposite to the rise path 8b. In this way, the outlet 244 is disposed on an outer periphery of the downward flow passage 34 in side-by-side relation to and independently of the inlet 40. Thus, the delaying flow passage 228 is a bypass-type delaying flow passage in which the entrance 40 and the exit 244 are separately arranged to form a bypass flow passage for flush water in a reservoir chamber. Based on the above structure, the delaying flow passage 228 makes it possible to enable flush water having flowed therein along the guide portion 32 of the flow dividing section 26 to merge with a flush water flow reaching the flow dividing section 26 at a timing after the inflow of the flush water to the delaying flow passage 228. The first extended flow passage 248a extending from the connection zone 246 to the first exit 244a and the second extended flow passage 248b extending from the connection zone 246 to the second exit 244b are formed as independent flow passages.

With reference to FIGS. 1A, 1B and 10, an operation (function) pertaining to the delaying flow passage in the second modification of the flush toilet according to the first embodiment will be described below.

Specifically, a state when draining is performed along with toilet flushing in the second modification of the flush toilet according to the first embodiment will be described with reference to FIGS. 1A, 1B and 10. In FIGS. 1A, 1B and 10, a flow of leading flush water, i.e., relatively low-speed flush water flowing on a leading side of waste C, is indicated by the arrowed lines A (A0 to A4, A9 and A10), and a waste conveyance flow, i.e., relatively high-speed flush water mainly flowing on a trailing side of the waste C to wash down or convey the waste C, is indicated by the arrowed lines B (B0 to B4). In the following description about the operation in the second modification, the same element or component as that in the above first embodiment is also assigned with the same reference numeral or sign, and its description will be omitted.

Firstly, a state in which relatively low-speed flush water is flowing on the leading side of the waste C will be described.

As depicted in FIG. 1A, the relatively low-speed leading flush water A has weak momentum, and thus flows down along part of an inner peripheral surface 8e of the fall path 8c on the side of the rise path 8b, as indicated by the arrowed line A1. Further, the leading flush water A flows down from the inner peripheral surface 8e into the discharge socket 16 smoothly along an introduction surface 34b of the flow dividing section 26, and is then guided along the guide portion 32 so as to flow from the introduction surface 34b toward the delaying flow passage 228, as indicated by the arrowed line A2. As depicted in FIG. 10, at least part of the leading flush water A flows into the entrance 40 of the delaying flow passage 228, as indicated by the arrowed lines A3. In this process, the leading flush water A flows down through part of the downward flow passage 34 on the side of the rise path 8b, so that flowing into the exit 244 can be suppressed. The leading flush water A having flowed into the delaying flow passage 228, as indicated by the arrowed lines A4. The flow direction of the leading flush water A is changed within the connection zone 246, so that the flow speed of the leading flush water A is reduced as compared to that at a timing of the inflow to the delaying flow passage 228.

The connection zone 246 and the extended flow passage 248 form a bypass flow passage. Thus, after the leading flush water A flows forwardly through the extended flow passage 248, the leading flush water A turns around rearwardly and flows toward the exit 244 of the extended flow passage 248, as depicted in the arrowed lines A9. The extended flow passage 248 forms a flow passage returning to the downward flow passage 34. Then, the leading flush water A flows toward the exit 244, and flows out toward the downward flow passage 34 through the exit 244, as indicated by the arrowed line A10.

Secondly, a waste conveyance flow for washing down waste will be described.

As depicted in FIG. 1B, a main stream of the waste conveyance flow B with the waste C flows down along part of a peripheral wall of the fall path 8c on the side opposite to the rise path 8b, as indicated by the arrowed line B1. Then, the main stream of the waste conveyance flow B with the waste C as indicated by the arrowed line B1 flows at a timing later than the leading flush water A as indicated by the arrowed line A1. The main stream of the waste conveyance

flow B with the waste C passes by a cutout-like portion 36 of the peripheral wall 34a of the downward flow passage 34, as indicated by the arrowed line B2. The main stream of the waste conveyance flow B with the waste C further flows down through the downward flow passage 34 as indicated by the arrowed line B3, so that colliding with the bottom wall surface 50 of the delaying flow passage 228 and flowing into the delaying flow passage 228 can be suppressed.

As depicted in FIG. 10, the leading flush water A flowing out to the downward flow passage 34 through the exit 244 merges with the main stream of the waste conveyance flow B with the waste C, as indicated by the arrowed line A10. As mentioned above, the leading flush water A having flowed into the delaying flow passage 228 passes through the bypass flow passage comprising the connection zone 246 and the extended flow passage 248 and having a given distance, until it flows out toward the downward flow passage 34 through the exit 244. In this process, a given time has elapsed. Further, the leading flush water A passing through the bypass flow passage has a relatively low flow speed, and the waste conveyance flow B as a trailing flow has a relatively high flow speed. Thus, the leading flush water A having flowed into the delaying flow passage 228 merges with the waste conveyance flow B reaching the downward flow passage 34 of the flow dividing section 26 at a delayed timing after an elapse of a given time since the inflow of the leading flush water A to the delaying flow passage 228, at a given position of the downward flow passage 34. That is, part of the leading flush water A having flowed into the delaying flow passage 228 is converted to the waste conveyance flow B. This makes it possible to add the leading flush water A contributing less to conveyance of the waste C, to the waste conveyance flow B, and thus increase the volume of the waste conveyance flow B as indicated by the arrowed line B4, thereby improving a capability of conveying the waste C (waste conveyance capability). The arrowed line B4 indicates the improved waste conveyance flow B which is increased in terms of flow rate and/or volume based on merging of the leading flush water A and the waste conveyance flow B.

Next, with reference to FIG. 11, a third modification of the flush toilet according to the first embodiment will be described.

In the third modification, the same element or component as that in the above first embodiment is assigned with the same reference numeral or sign, and its description will be omitted.

In the first embodiment, the discharge socket 16 communicated with the discharge trap pipe 8 and configured to discharge waste to the downstream building sewer pipe 22 is a resin member which is a separate component from the toilet main unit 2. However, the first embodiment may be modified to comprise a discharge conduit 316 which is one element integrally formed with the toilet main unit 2. The toilet main unit 2 and the discharge conduit 316 integrally formed together may be made of a ceramic material or may be made of a resin material.

Specifically, as depicted in FIG. 11, a flush toilet 301 in the third modification comprises a discharge socket 316 communicated with a discharge trap pipe 8 and configured to discharge waste to a downstream building sewer pipe 22. The discharge socket 316 is a member made of a ceramic material and formed as one element integral with a toilet main unit 2.

The discharge socket 316 comprises an upstream discharge conduit section 24, a flow dividing section 26, a delaying flow passage 28, and a downstream discharge

conduit section 30, which are arranged approximately in this order in a direction from an upstream end to a downstream end thereof. A fall path 8c of a discharge trap pipe 8 and the upstream discharge conduit section 24 of the discharge socket 316 are connected as an integral member, and thus an outlet 8d of the discharge trap pipe 8 is formed such that an inner peripheral surface 8e thereof is approximately flush with an introduction surface 34b of the flow dividing section 26 of the discharge socket 316.

In the flush toilet (1, 301) according to the first embodiment and the modifications thereof (hereinafter referred to collectively as "first embodiment"), during toilet flushing, the guide portion 32 of the flow dividing section 26 guide at least part of relatively low-speed flush water flowing on the leading side of waste (leading flush water) to the delaying flow passage (28, 128, 228), and the delaying flow passage (28, 128, 228) enables the leading flush water having flowed thereinto to merge with a flow of the relatively high-speed flush water for washing down or convey the waste (waste conveyance flow), which reaches the flow dividing section 26 at a timing after the inflow of the leading flush water to the delaying flow passage (28, 128, 228). This makes it possible to increase the volume of the waste conveyance flow to thereby improve the waste conveyance capability.

Further, in the flush toilet (1, 301) according to the first embodiment, it is possible to guide the high-speed waste conveyance to the downstream discharge conduit section (30, 130) so as not to guide the waste conveyance flow along the guide portion 32 to the delaying flow passage (28, 128, 228). This can make it less likely for the waste conveyance flow to flow into the delaying flow passage (28, 128, 228), while selectively enabling the low-speed leading flush water to flow into the delaying flow passage (28, 128, 228).

In the flush toilet (1, 301) according to the first embodiment, during toilet flushing, the low-speed leading flush water flows down through a specific part of the downward flow passage 34 on the side of the rise path 8b of the discharge trap pipe 8, because the momentum of the low-speed flush water is relatively weak. On the other hand, during toilet flushing, when the high-speed waste conveyance flow flows from the rise path 8b into the fall path 8c of the discharge trap pipe 8 and then into the downward flow passage 34 of the flow dividing section 26, the high-speed waste conveyance flow flows down through the remaining part of the peripheral wall 34a of the downward flow passage 34 on the side opposite to the rise path 8b of the discharge trap pipe 8, because the momentum of the high-speed waste conveyance flow is relatively strong. This can make it less likely for the waste conveyance flow to flow into the delaying flow passage (28, 128, 228), while selectively enabling the low-speed leading flush water to flow into the delaying flow passage (28, 128, 228). This makes it possible to more efficiently enable the low-speed leading flush water to flow into the delaying flow passage (28, 128, 228) and then merge with the waste conveyance flow.

In the flush toilet (1, 301) according to the first embodiment, as compared to case where the guide portion 32 of the flow dividing section 26 forms an angle of 90 degrees or more with respect to the vertical line Z, a change in direction between the guide portion 32 of the flow dividing section 26 and the downward flow passage 34 is reduced. Thus, it is possible to make it less likely for the leading flush water to separate from the guide portion 32. This makes it possible to more efficiently guide the leading flush water to the delaying flow passage (28, 128, 228).

In the flush toilet (1, 301) according to the first embodiment, the guide portion 32 of the flow dividing section 26 is

formed on the peripheral wall 34a defining the downward flow passage 34, on the side of the rise path 8b of the discharge trap pipe 8, and forms a cutout portion on the peripheral wall 34a on the side opposite to the rise path 8b. Thus, it becomes possible to enable the high-speed waste conveyance flow to pass through the cutout-like portion 36 so as to suppress the high-speed waste conveyance flow to flow from the guide portion 32 into the delaying flow passage (28, 128, 228).

In the flush toilet (1, 301) according to the first embodiment, the connection portion between the peripheral wall 34a defining the downward flow passage 34 and the guide portion 32 of the flow dividing section 26 is formed to have a curved surface, so that it is possible to make it less likely for a flow of the leading flush water to separate from the connection portion between the peripheral wall 34a and the guide portion 32. This makes it possible to further increase the volume of flush water to be enabled to flow into the delaying flow passage (28, 128, 228), i.e., further increase the volume of flush water to be enabled to merge with the waste conveyance flow.

In the flush toilet (1, 301) according to the first embodiment, flush water separating and dropping from the guide portion 32 of the flow dividing section 26 can be received and introduced into the delaying flow passage (28, 128, 228) by the bottom wall surface 50 of the delaying flow passage (28, 128, 228). This makes it possible to further increase the volume of flush water to be enabled to flow into the delaying flow passage (28, 128, 228), i.e., further increase the volume of flush water to be enabled to merge with the waste conveyance flow.

In the flush toilet (1, 301) according to the first embodiment, flowing the high-speed waste conveyance flow from the bottom wall surface 50 of the delaying flow passage (28, 128, 228) into the delaying flow passage (28, 128, 228) can be suppressed. This makes it possible to suppress a decrease in kinetic energy of the waste conveyance flow.

In the flush toilet (1, 301) according to the first embodiment, the introduction surface 34b extends approximately vertically from the upper end of the downward flow passage 34 to the upper end of the guide portion 32, so that it is possible to guide the low-speed leading flush water to the guide portion 32 along the introduction surface 34b. This makes it possible to further increase the volume of the low-speed leading flush water which flows into the delaying flow passage (28, 128, 228) along the guide portion 32.

In the flush toilet (1, 301) according to the first embodiment, the discharge conduit 16 is a resin member which is a separate component from the toilet main unit 2, so that it becomes possible to easily perform fine adjustment of the position of the discharge socket 16 depending on the position of the downstream building sewer pipe 22.

In the flush toilet (1, 301) according to the first embodiment, the inner peripheral surface 8e of the outlet 8d of the discharge trap pipe 8 is formed so as to be approximately flush with the introduction surface 34b of the flow dividing section 26 of the discharge socket 16. Thus, even in the case where the discharge socket 16 and the discharge trap pipe 8 are formed, respectively, as separate members, it is possible to reliably enable the low-speed leading flush water to flow along the introduction surface 34b. This makes it possible to further increase the volume of the low-speed leading flush water which flows into the delaying flow passage (28, 128, 228) via the introduction surface 34b and the guide portion 32.

Next, with reference to FIGS. 12 to 14, a flush toilet 401 according to a second embodiment of the present invention will be described.

In the second embodiment, the same element or component as that in the flush toilet 1 according to the above first embodiment is assigned with the same reference numeral or sign, and its description will be omitted.

Differently from the structure of the flush toilet 1 according to the first embodiment, wherein the guide portion 32 and the delaying flow passage 28 are arranged forward of the vertically-extending flow dividing section 26, a flush toilet 401 according to the second embodiment is configured such that a guide portion 432 and a delaying flow passage 428 are arranged on a lateral side of (in a rightward-leftward direction with respect to) a transversely-extending flow dividing section 426, as described below.

The flush toilet 401 comprises a discharge socket 416 communicated with a discharge trap pipe 8 and configured to discharge waste to a building sewer pipe 22 on a downstream side thereof.

The discharge socket 416 comprises an upstream discharge conduit section 424, a flow dividing section 426, a delaying flow passage 428, and a downstream discharge conduit section 430, which are arranged approximately in this order in a direction from an upstream end to a downstream end thereof. The discharge socket 416 is a resin member which is a separate component from a toilet main unit 2.

The upstream discharge conduit section 424 has an upstream end connected to an outlet 8d of the discharge trap pipe 8 (i.e., outlet 8d of a fall path 8c of the discharge trap pipe 8), and extends approximately parallel to the outlet 8d and vertically downwardly. The upstream discharge conduit section 424 extends from a position outside and above the outlet 8d of the fall path 8c to a bent portion 424a as a lower portion thereof.

The downstream discharge conduit section 430 is provided on a downstream side of the flow dividing section 426 extending in a transverse direction. The downstream discharge conduit section 430 extends vertically downwardly from a bent portion 430a thereof. The downstream discharge conduit section 430 has a downstream end connected to the building sewer pipe 22 which is disposed below a floor F on which the toilet main unit 2 is placed (see FIG. 1A).

The flow dividing section 426 is provided on a downstream side of the upstream discharge conduit section 424. The flow dividing section 426 is a linear flow passage extending transversely between the upstream discharge conduit section 424 and the downstream discharge conduit section 430. The flow dividing section 426 has a guide portion 432 configured to guide therealong at least part of relatively low-speed flush water (leading flush water) supplied from the discharge trap pipe 8 so as to flow into the delaying flow passage 428. The flow dividing section 426 has a transverse flow passage 434 located inward of the guide portion 432 to extend from an upper end to a lower end of the flow dividing section 426 in an approximately transverse direction.

The guide portion 432 of the flow dividing section 426 is formed on laterally opposite regions (right and left regions) of a peripheral wall 434a of the transverse flow passage 434, and formed between the transverse flow passage 434 and the delaying flow passage 428. The guide portion 432 is disposed on a lateral side of the transverse flow passage 434. The guide portion 432 extends from an upstream end thereof toward a downstream side to expand the flow passage. The guide portion 432 is formed such that a downstream end

thereof is oriented toward an inside of the delaying flow passage 428. The guide portion 432 forms an acute angle $\alpha 2$ with respect to a two-dot chain line Z2 along the transverse flow passage 434 (or a central axis of the transverse flow passage 434). The angle $\alpha 2$ may be set in the range of 5 to 60 degrees, preferably in the range of 5 to 45 degrees, more preferably to 30 degrees. Between the downstream end of the guide portion 432 and a downstream surface 450 of an entrance 440 of the delaying flow passage 428, an inflow opening is formed.

As depicted in FIG. 14, the guide portion 432 is formed on the right and left regions of the peripheral wall 434a of the transverse flow passage 434. The guide portion 432 is formed along approximately one-half or more of the entire circumference of the peripheral wall 434a of the transverse flow passage 434.

As depicted in FIG. 13, a connection portion 438 between the peripheral wall 434a of the transverse flow passage 434 and the guide portion 432 of the flow dividing section 426 is formed to have a smoothly curved surface. The peripheral wall 434a of the transverse flow passage 434 of the flow dividing section 426 is formed to have an introduction surface 434b which extends approximately linearly in a transverse direction to the upstream end of the guide portion 432.

As depicted in FIGS. 12 to 14, the delaying flow passage 428 is formed as a flow passage branched rightwardly and leftwardly from the flow dividing section 426. The delaying flow passage 428 forms a flow passage in a lateral region E. The delaying flow passage 428 is disposed on a lateral side of the guide portion 432. The delaying flow passage 428 is formed bilaterally symmetrically with respect to a longitudinal axis of the toilet main unit 2. Although the delaying flow passage 428 is disposed on the right and left sides with respect to the flow dividing section 426, it is to be understood that it may be disposed on only one of the right and left sides with respect to the flow dividing section 426.

The delaying flow passage 428 comprises a connection zone 446 connecting with the flow dividing section 426, and an extended flow passage 448 extending from the connection zone 446 toward the lateral region E.

The connection zone 446 has an entrance 440 for accepting flush water guided along the guide portion 432. This entrance 440 also functions as an exit 444 for enabling flush water having flowed into the connection zone 446 to flow out therefrom. The connection zone 446 further functions as a reservoir chamber for enabling flush water having flowed thereinto from the entrance 440 to flow thereinside so as to temporarily stay therein. The entrance 440 is located downstream and outside the guide portion 432. The entrance 440 is located on the lateral side of the transverse flow passage 434 of the flow dividing section 426, and formed as an opening including about a lower half of the entire circumference of the peripheral wall 434a of the transverse flow passage 434. That is, the delaying flow passage 428 is a reservoir-type delaying flow passage in which a single opening is used as both of the entrance 440 and the exit 444, and flush water temporarily stays therein while flowing thereinside. Further, the connection zone 446 forms a bent flow passage for changing a flow direction of flush water having flowed thereinto from the flow dividing section 426, toward the lateral region E on a lateral side thereof. The connection zone 446 forming the bent flow passage makes it possible to reduce the flow speed of flush water flowing thereinside. Thus, by enabling flush water to flow inside the connection zone 446, it becomes possible to delay a timing at which this flush water flows through the discharge socket

416, with respect to an initial state. Based on this mechanism, the delaying flow passage 428 makes it possible for flush water having flowed thereto along the guide portion 432 of the flow dividing section 426 to merge with a flush water flow reaching the flow dividing section 426 at a timing after the inflow of the flush water to the delaying flow passage 428, in a delayed manner. The connection zone 446 and the extended flow passage 448 are formed such that a bottom wall thereof is like a plane and slightly inclines downwardly toward the entrance 440.

The extended flow passage 448 is provided in each of first and second side regions of the lateral region E on both sides of a central region D. Alternatively, the extended flow passage 448 may be provided in only one of the first and second side regions of the lateral region E on both sides of the central region D. Further, although the extended flow passage 448 in the second embodiment is provided only in the lateral region E, the extended flow passage 448 may be provided in each of the central region D and the lateral region E. The extended flow passage 448 extends in a direction along the discharge trap pipe 8, i.e., a forward-rearward (longitudinal) direction of the toilet main unit 2. In side view, the extended flow passage 448 extends from a position beneath the fall path 8c of the discharge trap pipe 8 to a position corresponding to a front end of the discharge trap pipe 8. The extended flow passage 448 extends the delaying flow passage 428 to an inside of the lateral region E. The extended flow passage 448 expands the delaying flow passage 428 to a wider region in the lateral region E to increase a bottom surface area of the delaying flow passage 428. The bottom surface area of the delaying flow passage 428 is increased by the extended flow passage 448, as mentioned above. Thus, even in a situation where the flow speed of inflowing flush water is fairly low, it is possible to make it easier to enable the flush water to flow into a wider region of the delaying flow passage 428, and thus make it easier to enable the flush water to flow into the delaying flow passage 428 in a larger volume, as compared to case where the delaying flow passage 428 has a smaller bottom surface area. Thus, by forming the delaying flow passage 428 in the lateral region E to increase the bottom surface area of the delaying flow passage 428 in the lateral region E, it becomes possible to more reliably increase the volume of flush water flowing through the delaying flow passage, irrespective of the flow speed of inflowing flush water. The extended flow passage 448 additionally functions as a reservoir chamber for allowing flush water to temporarily stay therein. The extended flow passage 448 is configured to reduce the flow speed of flush water having flowed thereto, during a course in which flush water having flowed thereto from the connection zone 446 flows therethrough while turning back toward the connection zone 446.

As depicted in FIG. 13, the delaying flow passage 428 is formed such that a downstream surface 450 defining the entrance 440 thereof protrudes inside the flow dividing section 426 to a position downstream of and opposed to the guide portion 432 of the flow dividing section 426. An edge 450a of the downstream surface 450 of the delaying flow passage 428 is located outward of the transverse flow passage 434, in side view as viewed from an upstream end of the transverse flow passage 434.

In the second embodiment, the discharge socket 416 communicated with the discharge trap pipe 8 and configured to discharge waste to the downstream building sewer pipe 22 is a resin member which is a separate component from the toilet main unit 2. However, the second embodiment may be modified to comprise a discharge conduit which is one

element integrally formed with the toilet main unit 2. The toilet main unit 2 and the discharge conduit integrally formed together may be made of a ceramic material or may be made of a resin material.

5 With reference to FIGS. 1A, 1B and 12 to 14, an operation (function) of the flush toilet according to the second embodiment will be described below.

Specifically, a state when draining is performed along with toilet flushing in the flush toilet according to the second embodiment will be described with reference to FIGS. 1A, 1B and 12 to 14. In FIGS. 1A, 1B, 12 and 13, a flow of leading flush water, i.e., relatively low-speed flush water flowing on a leading side of waste C, is indicated by the arrowed lines A (A0, A1, A11 to A 17), and a waste conveyance flow, i.e., relatively high-speed flush water mainly flowing on a trailing side of the waste C to wash down or convey the waste C, is indicated by the arrowed lines B (B0, B1, B7 to B11). The toilet main unit 2 of the flush toilet 401 according to the second embodiment is 10 approximately the same as that of the toilet main unit 2 of the flush toilet 1 according to the first embodiment. Thus, a flow of flush water in the toilet main unit 2 of the flush toilet 401 will be described primarily with reference to FIGS. 1A and 1B. Further, in the second embodiment, the same 15 element or component as that of the flush toilet 1 according to the first embodiment is assigned with the same reference numeral or sign, and its description will be omitted.

Firstly, a state in which relatively low-speed flush water is flowing on the leading side of the waste C will be 20 described.

As depicted in FIG. 1A, at a start of toilet flushing in the flush toilet 401, relatively low-speed flush water A flows on the leading side of the waste C, as indicated by the arrowed line A0. The relatively low-speed leading flush water A has 25 weak momentum, and thus flows down along part of the inner peripheral surface 8e of the fall path 8c on the side of an rise path 8b, as indicated by the arrowed line A1.

The leading flush water A having flowed down into the upstream discharge conduit section 424 flows downwardly 30 as indicated by the arrowed line A11 in FIG. 12, and then flows into the flow dividing section 426. The leading flush water A having flowed down into the flow dividing section 426 flows transversely through the transverse flow passage 434, as indicated by the arrowed lines A12 in FIG. 13. The leading flush water A has a relatively low flow rate, so that 35 it is more likely to spread laterally in the transverse flow passage 434. The leading flush water A flows along the peripheral wall 434a of the transverse flow passage 434 toward the guide portion 432 via the introduction surface 434b, and is then guided along the guide portion 432 toward the delaying flow passage 428, as indicated by the arrowed lines A13. The leading flush water A is drawn to the guide portion 432 by the Coanda effect, so that a flow direction 40 thereof is changed to a direction along which the guide portion 432 extends. In this way, at least part of the leading flush water A flows into the entrance 440 of the delaying flow passage 428, as indicated by the arrowed lines A14. The leading flush water A having flowed into the connection zone 446 flows from the connection zone 446 toward the extended flow passage 448, as indicated by the arrowed lines 45 A15. The flow direction of the leading flush water A is changed within the connection zone 446, so that the flow speed of the leading flush water A is reduced as compared to that at a timing of the inflow to the delaying flow passage 428. As a result of flowing through the connection zone 446 and the extended flow passage 448, the leading flush water A is delayed with respect to a flow of flush water flowing

through the transverse flow passage 434 as a main flow passage. The leading flush water A gently flows in such a manner as to be temporarily held in the connection zone 446 and the extended flow passage 448, and then returns to the main stream. When the volume of flush water flowing into the entrance 440 of the delaying flow passage 428 becomes small or zero after elapse of a given time from the start of toilet flushing, the leading flush water A having flowed into the connection zone 446 and the extended flow passage 448 flows toward the exit 444 and then flows out toward the transverse flow passage 434 through the exit 444, as indicated by the arrowed lines A16.

Secondly, a waste conveyance flow for washing down waste will be described.

As depicted in FIGS. 1A and 1B, at a start of toilet flushing, according to a water flow action caused by drop of flush water from a water conducting passage 6 to a water pooling region 14, a waste conveyance flow B for strongly washing down waste is formed.

The waste conveyance flow B acting to wash down the waste C flows around the waste C and mainly on the trailing side of the waste C, as indicated by the arrowed line B0. A main stream of the waste conveyance flow B with the waste C flows down along part of a peripheral wall of the fall path 8c on the side opposite to the rise path 8b, as indicated by the arrowed line B1. Then, the main stream of the waste conveyance flow B with the waste C as indicated by the arrowed line B1 flows at a timing later than the leading flush water A as indicated by the arrowed line A1. The main stream of the waste conveyance flow B with the waste C, having flowed down into the upstream discharge conduit section 424, flows downwardly as indicated by the arrowed line B7 in FIG. 12, and then flows into the flow dividing section 426. The main stream of the waste conveyance flow B with the waste C, having flowed into the flow dividing section 426, flows transversely through the transverse flow passage 434, as indicated by the arrowed lines B8 in FIG. 13. The main stream of the waste conveyance flow B with the waste C has a relatively high flow rate, so that it is less likely to spread laterally in the transverse flow passage 434, i.e., tends to flow straight through the transverse flow passage 434. Thus, the main stream of the waste conveyance flow B with the waste C flows straight as indicated by the arrowed lines B9, so that it is less likely to be guided along the guide portion 432 toward the delaying flow passage 428. In this process, the main stream of the waste conveyance flow B with the waste C as indicated by the arrowed lines B9 passes through a cutout-like portion formed in lower region of the peripheral wall 434a of the transverse flow passage 434. The main stream of the waste conveyance flow B with the waste C further flows down through the transverse flow passage 434 as indicated by the arrowed lines B10, so that colliding with the downstream surface 450 of the entrance 440 of the connection zone 446 and flowing into the delaying flow passage 428 can be suppressed.

As regards the leading flush water A having a relatively low flow speed, a relatively large proportion by volume of leading flush water A flowing from the upstream discharge conduit section 424 is guided to the delaying flow passage 428 along the guide portion 432. On the other hand, as regards the waste conveyance flow B having a relatively high flow speed, a relatively small proportion by volume of a waste conveyance flow B flowing from the upstream discharge conduit section 424 is guided to the delaying flow passage 428 along the guide portion 432. Thus, a rate of part of the leading flush water A to be guided to the delaying flow passage 428 along the guide portion 432 is greater than a rate

of part of the waste conveyance flow B to be guided to the delaying flow passage 428 along the guide portion 432. In this case, the rate of the part of the waste conveyance flow B to be guided to the delaying flow passage 428 along the guide portion 432 is 0% or more.

The leading flush water A flowing out to the transverse flow passage 434 through the exit 444 merges with the waste conveyance flow B, as indicated by the arrowed lines A17. As mentioned above, the leading flush water A having flowed into the connection portion 446 flows inside the delaying flow passage 428 until it flows out toward the transverse flow passage 434 through the exit 444. In this process, a given time has elapsed. Thus, the leading flush water A in the delaying flow passage 428 merges with the waste conveyance flow B reaching the transverse flow passage 434 of the flow dividing section 426 at a timing after a given time has elapsed since the inflow of the leading flush water A to the delaying flow passage 428. That is, part of the leading flush water A having flowed into the delaying flow passage 428 is converted to the waste conveyance flow B.

This makes it possible to add the leading flush water A contributing less to conveyance of the waste C, to the waste conveyance flow B, and thus increase the volume of the waste conveyance flow B as indicated by the arrowed lines B11, thereby improving a capability of conveying the waste C (waste conveyance capability). The arrowed lines B11 indicate the improved waste conveyance flow B which is increased in terms of flow rate and/or volume based on merging of the leading flush water A and the waste conveyance flow B.

The improved waste conveyance flow B with the waste C flows toward the downstream discharge conduit section 430, and is then discharged into the building sewer pipe 22.

In the flush toilet 401 according to the second embodiment, during toilet flushing, the guide portion 432 of the flow dividing section 426 guide relatively low-speed flush water flowing on the leading side of waste (leading flush water) to the delaying flow passage 428, and the delaying flow passage 428 enables the leading flush water having flowed thereto to merge with a flow of the relatively high-speed flush water for washing down or convey the waste (waste conveyance flow), which reaches the flow dividing section 426 at a timing after the inflow of the leading flush water to the delaying flow passage 428. This makes it possible to increase the volume of the waste conveyance flow to thereby improve the waste conveyance capability.

Further, in the flush toilet 401 according to the second embodiment, it is possible to guide the high-speed waste conveyance flow to the downstream discharge conduit section 430 so as not to guide the waste conveyance flow along the guide portion 432 to the delaying flow passage 428. This can make it less likely for the waste conveyance flow to flow into the delaying flow passage 428, while selectively enabling the low-speed leading flush water to flow into the delaying flow passage 428.

In the flush toilet 401 according to the second embodiment, the waste conveyance flow having a relatively high flow speed is less likely to spread laterally in the transverse flow passage 434, and thus flows through the transverse flow passage 434 approximately straightforwardly. On the other hand, the leading flush water having a relatively low flow speed is more likely to spread laterally in the transverse flow passage 434. Thus, in the flow dividing section 426, the transverse flow passage 434 can make it less likely for the waste conveyance flow to flow into the delaying flow passage 428, and the guide portion 432 can efficiently

selectively enable the leading flush water to flow into the delaying flow passage 428 extending laterally from the transverse flow passage 434.

In the flush toilet 401 according to the second embodiment, the connection portion between the peripheral wall 434a of the transverse flow passage 434 and the guide portion 432 of the flow dividing section 426 is formed to have a curved surface, so that it is possible to make it less likely for a flow of the leading flush water to separate from the connection portion between the peripheral wall 434a of the transverse flow passage 434 and the guide portion 432. This make it possible to further increase the volume of flush water to be enabled to flow into the delaying flow passage 428, i.e., further increase the volume of flush water to be enabled to merge with the waste conveyance flow.

In the flush toilet 401 according to the second embodiment, flush water separating from the guide portion 432 of the flow dividing section 426 and flowing toward the downstream side can be received and introduced into the delaying flow passage 428 by the downstream surface 450 of the delaying flow passage 428. This make it possible to further increase the volume of flush water to be enabled to flow into the delaying flow passage 428, i.e., further increase the volume of flush water to be enabled to merge with the waste conveyance flow.

In the flush toilet 401 according to the second embodiment, it is possible to suppress a situation where the downstream surface 450 of the delaying flow passage 428 causes the high-speed waste conveyance flow being flowing toward the downstream side through the transverse flow passage 434 of the flow dividing section 426 to undesirably flow into the delaying flow passage 428. This makes it possible to suppress a decrease in kinetic energy of the waste conveyance flow.

In the flush toilet 401 according to the second embodiment, the discharge socket 416 is a resin member which is a separate component from the discharge trap pipe 8, so that it becomes possible to easily perform fine adjustment of the position of the discharge socket 416 depending on the position of the downstream building sewer pipe 22.

Next, with reference to FIGS. 15 to 17, a flush toilet 501 according to a second embodiment of the present invention will be described.

In the third embodiment, the same element or component as that in the flush toilet 1 according to the above first embodiment is assigned with the same reference numeral or sign, and its description will be omitted.

Differently from the structure of the flush toilet 1 according to the first embodiment, wherein the delaying flow passage 28 is disposed forward of the vertically-extending flow dividing section 26, a flush toilet 501 according to the third embodiment is configured such that a delaying flow passage 528 is disposed inside a transversely-extending downstream discharge conduit section 530, as described below.

The flush toilet 501 comprises a discharge socket 516 communicated with a discharge trap pipe 8 and configured to discharge waste to a building sewer pipe 22 on a downstream side thereof.

The discharge socket 516 comprises an upstream discharge conduit section 524, a flow dividing section 526, a delaying flow passage 528, and a downstream discharge conduit section 530, which are arranged approximately in this order in a direction from an upstream end to a downstream end thereof. The discharge socket 516 is a resin member which is a separate component from a toilet main unit 2.

The upstream discharge conduit section 524 has an upstream end connected to an outlet 8d of the discharge trap pipe 8 (i.e., outlet 8d of a fall path 8c of the discharge trap pipe 8), and extends approximately parallel to the outlet 8d and vertically downwardly. The upstream discharge conduit section 524 extends from a position outside and above the outlet 8d of the fall path 8c to a position below the outlet 8d.

The downstream discharge conduit section 530 is provided on a downstream side of the flow dividing section 526. The downstream discharge conduit section 530 forms a transverse flow passage linearly extending linearly in a transverse direction from a downstream end of the flow dividing section 526 to the position of the building sewer pipe 22. The downstream discharge conduit section 530 has a downstream end connected to the building sewer pipe 22 which is disposed below a floor F on which the toilet main unit 2 is placed.

The flow dividing section 526 is provided on a downstream side of the upstream discharge conduit section 524. The flow dividing section 526 is formed in an upper region of a bent section between the upstream discharge conduit section 524 and the downstream discharge conduit section 530. The flow dividing section 526 has a guide portion 532 configured to guide therealong at least part of relatively low-speed flush water (leading flush water) supplied from the discharge trap pipe 8 so as to flow into the delaying flow passage 528. The flow dividing section 526 has a downward flow passage 534 located inward of the guide portion 532 to extend from an upper end to a lower end of the flow dividing section 526 in an approximately vertical direction.

The guide portion 532 of the flow dividing section 526 is formed to extend from part of a peripheral wall 534a of the downward flow passage 534 on the side of a rise path 8b of the discharge trap pipe 8, and formed between the downward flow passage 534 and the delaying flow passage 528. The guide portion 532 is disposed forward of the downward flow passage 534. The guide portion 532 has a curved surface formed to extend obliquely downwardly from an upper end thereof and have lower end expanding toward an inside of the delaying flow passage 528. The guide portion 532 forms an acute angle α_3 with respect to a vertical line Z. The angle α_3 may be set in the range of 5 to 60 degrees, preferably in the range of 5 to 45 degrees, more preferably to 30 degrees. Between a lower end of the guide portion 532 and a bottom wall surface 550 of the delaying flow passage 528, an inflow opening is formed.

As depicted in FIG. 16, the guide portion 532 is formed to extend from a specific part of the peripheral wall 534a of the downward flow passage 534 on the side of the rise path 8b of the discharge trap pipe 8, and the remaining part of the peripheral wall 534a on a side opposite to the rise path 8b is formed as a cutout-like portion 536 which provides a cutoff space in the downward flow passage 534 between one side end and the other side end of the guide portion 532. The guide portion 532 is formed along approximately one-half of the entire circumference of the peripheral wall 534a of the downward flow passage 534. That is, the cutout-like portion 536 is formed by omitting formation of the guide portion 532 in the remaining part of the peripheral wall 534a on the side opposite to the rise path 8b. In FIG. 16, the cutout-like portion 536 is generally indicated by the two-dot chain line. The guide portion 532 is not formed in the cutout space along the cutout-like portion 536, so that a flow of relatively high-speed flush water for conveying waste (waste conveyance flow) is suppressed from colliding with the guide

portion 532, and thus flows down through the region of the cutout-like portion 536 while maintaining relatively strong momentum.

As depicted in FIG. 16, a connection portion 538 between the peripheral wall 534a of the downward flow passage 534 and the guide portion 532 of the flow dividing section 526 is formed to have a smoothly curved surface. The peripheral wall 534a of the downward flow passage 534 of the flow dividing section 526 is formed to have an introduction surface 534b which extends approximately vertically to the upper end of the guide portion 532.

The delaying flow passage 528 forms a flow passage branched from the flow dividing section 526. The delaying flow passage 528 is configured such that the leading flush water having flowed thereto from the flow dividing section 526 is enabled to merge with a flush water flow reaching the flow dividing section 526 at a timing after the inflow of the leading flush water to the delaying flow passage 528. The delaying flow passage 528 is disposed forward of the guide portion 532. The delaying flow passage 528 is formed bilaterally symmetrically with respect to a longitudinal axis of the toilet main unit 2.

The delaying flow passage 528 comprises a connection zone 546 connecting with the flow dividing section 526, and an extended flow passage 548 extending forwardly from the connection zone 546.

The connection zone 546 is connected to a specific part of the flow dividing section 526 on the side of the rise path 8b. The connection zone 546 has an entrance 540 for accepting flush water guided along the guide portion 532. This entrance 540 also functions as an exit 544 for enabling flush water having flowed into the connection zone 546 to flow out therefrom. The connection zone 546 further functions as a reservoir chamber for enabling flush water having flowed thereto from the entrance 540 to flow thereinside so as to temporarily stay therein until it flows out from the exit 544. The entrance 540 of the connection zone 546 is located below and outside the guide portion 532. The entrance 540 is formed as an opening including about one-half of the entire circumstance of the flow dividing section 526 on the side of the rise path 8b. The delaying flow passage 528 is a reservoir-type delaying flow passage in which a single opening is used as both of the entrance 540 and the exit 544, and flush water temporarily stays therein while flowing thereinside. The connection zone 546 forms a flow passage extending from the entrance 540 transversely with respect to the vertical direction, so that it is capable of reducing the flow speed of flush water flowing thereinside. Thus, by enabling flush water to flow inside the connection zone 546, it becomes possible to delay a timing at which this flush water flows through the discharge socket 516, with respect to an initial. Based on this mechanism, the delaying flow passage 528 makes it possible for flush water having flowed thereto along the guide portion 532 of the flow dividing section 526 to merge with a flush water flow reaching the flow dividing section 526 at a timing after the inflow of the flush water to the delaying flow passage 528, in a delayed manner.

The extended flow passage 548 is provided in a central region D. The extended flow passage 548 extends in a direction along the discharge trap pipe 8, i.e., in a forward-rearward (longitudinal) direction of the toilet main unit 2. The extended flow passage 548 is formed inside and in an upper region of the downstream discharge conduit section 530, over a given distance. More specifically, in side view, the extended flow passage 548 extends from a position beneath the fall path 8c of the discharge trap pipe 8 to a

position corresponding to a front end of the discharge trap pipe 8. The connection zone 546 and the extended flow passage 548 forms a space partitioned with respect to the downstream discharge conduit section 530. The extended flow passage 548 extends the delaying flow passage 528 to an inside of the central region D. The extended flow passage 548 increases a bottom surface area of the delaying flow passage 528. In this embodiment, the bottom surface area of the delaying flow passage 528 is increased by the extended flow passage 548, as mentioned above. Thus, even in a situation where the flow speed of inflowing flush water is fairly low, it is possible to make it easier to enable the flush water to flow into a wider region of the delaying flow passage 528, and thus make it easier to enable the flush water to flow into the delaying flow passage 528 in a larger volume, as compared to case where the delaying flow passage 528 has a smaller bottom surface area. The extended flow passage 548 additionally functions as a reservoir chamber for allowing flush water to temporarily stay therein. The extended flow passage 548 is configured to cause flush water having flowed thereto from the connection zone 546 to flow therethrough while turning back toward the connection zone 546, thereby reducing the flow speed of flush water having flowed thereto.

As depicted in FIG. 16, the delaying flow passage 528 is formed such that the bottom wall surface 550 thereof protrudes inside the flow dividing section 526 to reach a position below and opposed to the guide portion 532 of the flow dividing section 526. In top view, an edge 550a of the bottom wall surface 550 of the delaying flow passage 528 is located outward of an outer edge of the downward flow passage 534. The delaying flow passage 528 is formed such that the bottom wall surface 550 in the connection zone 546 and the extended flow passage 548 slightly inclines downwardly toward the entrance 540. This makes it possible to reduce the flow speed of inflowing flush water, and discharge water remaining in the delaying flow passage 528, toward the entrance 540.

With reference to FIGS. 1A, 1B and 15 to 17, an operation (function) of the flush toilet according to the third embodiment will be described below.

Specifically, a state when draining is performed along with toilet flushing in the flush toilet according to the third embodiment will be described with reference to FIGS. 1A, 1B and 15 to 17. In FIGS. 1A, 1B and 16, a flow of leading flush water, i.e., relatively low-speed flush water flowing on a leading side of waste C, is indicated by the arrowed lines A (A0, A1, A18 to A23), and a waste conveyance flow, i.e., relatively high-speed flush water mainly flowing on a trailing side of the waste C to wash down or convey the waste C, is indicated by the arrowed lines B (B0 to B3, B12). The toilet main unit 2 of the flush toilet 501 according to the third embodiment is approximately the same as that of the toilet main unit 2 of the flush toilet 1 according to the first embodiment. Thus, a flow of flush water in the toilet main unit 2 of the flush toilet 501 will be described primarily with reference to FIGS. 1A and 1B. Further, in the third embodiment, the same element or component as that of the flush toilet 1 according to the first embodiment is assigned with the same reference numeral or sign, and its description will be omitted.

Firstly, a state in which relatively low-speed flush water is flowing on the leading side of the waste C will be described.

As depicted in FIG. 1A, at a start of toilet flushing, relatively low-speed flush water A flows on the leading side of the waste C, as indicated by the arrowed line A0. The

relatively low-speed leading flush water A has weak momentum, and thus flows down along part of an inner peripheral surface **8e** of the fall path **8c** on the side of the rise path **8b**, as indicated by the arrowed line **A1**.

As depicted in FIG. 16, the leading flush water A flows down from the inner peripheral surface **8e** along the peripheral wall **534a** of the downward flow passage **534** of the flow dividing section **526**, as indicated by the arrowed line **A18**. Further, the leading flush water A smoothly flows down along the introduction surface **534b** of the flow dividing section **526**, and is then guided along the guide portion **532** so as to flow from the introduction surface **534b** toward the delaying flow passage **528**, as indicated by the arrowed line **A19**. The leading flush water A is drawn to the guide portion **532** by the Coanda effect, so that a flow direction thereof is changed to a direction along which the guide portion **532** extends. In this way, at least part of the leading flush water A flows into the entrance **540** of the connection zone **546** of the delaying flow passage **528**, as indicated by the arrowed line **A20**. The leading flush water A having flowed into the connection zone **546** flows from the connection zone **546** toward the extended flow passage **548**, as indicated by the arrowed lines **A21**. The flow speed of the leading flush water A having flowed into the connection zone **546** is reduced as compared to that at a timing of the inflow to the delaying flow passage **528**. Further, as a result of flowing through the connection zone **546** and the extended flow passage **548**, the leading flush water A is delayed with respect to a flow of flush water flowing through the downward flow passage **534** as a main flow passage. The leading flush water A gently flows in such a manner as to be temporarily held in the connection zone **546** and the extended flow passage **548**, and then returns to the main stream. When the volume of flush water flowing into the entrance **540** of the delaying flow passage **528** becomes small or zero after elapse of a given time from the start of toilet flushing, the leading flush water A in the connection zone **546** and the extended flow passage **548** flows toward the exit **544** as indicated by the arrowed line **A22**, and then flows out toward the downward flow passage **534** through the exit **544**.

Secondly, a waste conveyance flow for washing down waste will be described.

As depicted in FIGS. 1A and 1B, at a start of toilet flushing, according to a water flow action caused by drop of flush water from a water conducting passage **6** to a water pooling region **14**, a waste conveyance flow B for strongly washing down waste is formed.

The waste conveyance flow B acting to wash down the waste C flows around the waste C and mainly on the trailing side of the waste C, as indicated by the arrowed line **B0**. A main stream of the waste conveyance flow B with the waste C flows down along part of a peripheral wall of the fall path **8c** on the side opposite to the rise path **8b**, as indicated by the arrowed line **B1**. Then, the main stream of the waste conveyance flow B with the waste C as indicated by the arrowed line **B1** flows at a timing later than the leading flush water A as indicated by the arrowed line **A1**.

As depicted in FIG. 16, the main stream of the waste conveyance flow B with the waste C passes through the cutout-like portion **536** of the peripheral wall **534a** of the downward flow passage **534**, on the side opposite to the rise path **8b**, as indicated by the arrowed line **B2**. The main stream of the waste conveyance flow B with the waste C further flows down through the downward flow passage **534** as indicated by the arrowed line **B3**, so that it is suppressed

from colliding with the bottom wall surface **550** of the delaying flow passage **528** and flowing into the delaying flow passage **528**.

As regards the leading flush water A having a relatively low flow speed, a relatively large proportion by volume of leading flush water A flowing from the discharge trap pipe **8** is guided to the delaying flow passage **528** along the guide portion **532**. On the other hand, as regards the waste conveyance flow B having a relatively high flow speed, a relatively small proportion by volume of a waste conveyance flow B flowing from the discharge trap pipe **8** is guided to the delaying flow passage **528** along the guide portion **532**. Thus, a rate of part of the leading flush water A to be guided to the delaying flow passage **528** along the guide portion **532** is greater than a rate of part of the waste conveyance flow B to be guided to the delaying flow passage **528** along the guide portion **532**. In this case, the rate of the part of the waste conveyance flow B to be guided to the delaying flow passage **528** along the guide portion **532** is 0% or more.

The leading flush water A flowing out to the downward flow passage **534** through the exit **544** merges with the waste conveyance flow B, as indicated by the arrowed line **A23**. As mentioned above, the leading flush water A having flowed into the delaying flow passage **528** flows inside the delaying flow passage **528** until it flows out toward the downward flow passage **534** through the exit **544**. In this process, a given time has elapsed. Thus, the leading flush water A merges with the waste conveyance flow B reaching the downward flow passage **534** of the flow dividing section **526** at a timing after a given time has elapsed since the inflow of the leading flush water A to the delaying flow passage **528**. That is, part of the leading flush water A having flowed into the delaying flow passage **528** is converted to the waste conveyance flow B.

This makes it possible to add the leading flush water A contributing less to conveyance of the waste C, to the waste conveyance flow B, and thus increase the volume of the waste conveyance flow B as indicated by the arrowed line **B12**, thereby improving a capability of conveying the waste C (waste conveyance capability). The arrowed line **B12** indicates the improved waste conveyance flow B which is increased in terms of flow rate and/or volume based on merging of the leading flush water A and the waste conveyance flow B.

The improved waste conveyance flow B with the waste C flows toward the downstream side through the downstream discharge conduit section **530**, and is finally discharged into the building sewer pipe **22**.

In the flush toilet **501** according to the third embodiment, during toilet flushing, the guide portion **532** of the flow dividing section **526** guide relatively low-speed flush water flowing on the leading side of waste (leading flush water) to the delaying flow passage **528**, and the delaying flow passage **528** enables the leading flush water having flowed thereinto to merge with a flow of the relatively high-speed flush water for washing down or convey the waste (waste conveyance flow), which reaches the flow dividing section **526** at a timing after the inflow of the leading flush water to the delaying flow passage **528**. This makes it possible to increase the volume of the waste conveyance flow to thereby improve the waste conveyance capability.

Further, in the flush toilet **501** according to the third embodiment, it is possible to enable the high-speed waste conveyance flow to flow to the downstream discharge conduit section **530** so as not to guide the waste conveyance flow along the guide portion **532** to the delaying flow

passage 528. This can make it less likely for the waste conveyance flow to flow into the delaying flow passage 528, while selectively enabling the low-speed leading flush water to flow into the delaying flow passage 528.

The flush toilet 501 according to the third embodiment can bring out the same advantage effects as those in the flush toilet 1 according to the first embodiment. Thus, description about the remaining effects will be omitted.

It should be noted that the present invention is not limited to the above embodiment, but various modifications and changes may be made therein. For example, a flow dividing section and a delaying flow passage of the discharge socket in the flush toilet according to any one of the embodiments of the present invention are usable in a situation where the discharge trap pipe of the toilet main unit has various shapes, and/or the building sewer pipe is set at various positions.

FIG. 18A is a sectional view depicting a first type of flush toilet in which the flow dividing section and the delaying flow passage of the discharge socket in the flush toilet according to at least one of the embodiments of the present invention are suitably usable, wherein the first type of flush toilet comprises a discharge trap pipe opened to face a floor, and a discharge socket to be connected to a building sewer pipe extending from a building wall. FIG. 18B is a sectional view depicting a second type of flush toilet in which the flow dividing section and the delaying flow passage of the discharge socket in the flush toilet according to at least one of the embodiments of the present invention are suitably usable, wherein the second type of flush toilet comprises a discharge trap pipe opened to face a building wall, and a discharge socket to be connected to a building sewer pipe extending from the building wall. FIG. 18C is a sectional view depicting a third type of flush toilet in which the flow dividing section and the delaying flow passage of the discharge socket in the flush toilet according to at least one of the embodiments of the present invention are suitably usable, wherein the third type of flush toilet comprises a discharge trap pipe opened to face a building wall, and a discharge socket to be connected to a building sewer pipe extending from a floor.

As depicted in FIG. 18A, there is a situation where a discharge socket 616A connecting a toilet main unit T and a building sewer pipe P is formed in an approximately L shape in side view.

In this situation, the discharge socket 616A may be divided into a transverse section a1 communicable with a building sewer pipe P and extending in a transverse direction, and an approximately L-shaped bent section a2 communicable between the transverse section a1 and an outlet To of a vertically downwardly-extending discharge trap pipe of a toilet main unit T.

As one example, in the discharge socket 616A having the above shape, the flow dividing section 426 and the delaying flow passage 428 described in the second embodiment are suitably usable in the transverse section a1. As another example, in the discharge socket 616A, the flow dividing section 26 and the delaying flow passage (28, 228) in the first embodiment are suitably usable in the bent section a2. As yet another example, in the discharge socket 616A, the flow dividing section 526 and the delaying flow passage 528 in the third embodiment are suitably usable in the bent section a2.

As depicted in FIG. 18B, there is a situation where a discharge socket 616B connecting a toilet main unit T and a building sewer pipe P is formed as an transverse pipe communicable between the building sewer pipe P and an outlet To of a transversely-extending discharge trap pipe of

the toilet main unit T. As one example, in the discharge socket 616B having the above shape, the flow dividing section 426 and the delaying flow passage 428 described in the second embodiment are suitably usable in the transverse pipe.

As depicted in FIG. 18C, there is a situation where a discharge socket 616C connecting a toilet main unit T and a building sewer pipe P is formed in an approximately S shape in side view.

In this situation, the discharge socket 616C may be divided into: an approximately L-shaped first bent section c1 communicable with a horizontally-opened outlet To of a discharge trap pipe of a toilet main unit T; an approximately L-shaped second bent section c2 having one end communicable with the first bent section c1 and extending vertically and the other end extending horizontally; a transverse section c3 communicable with the second bent section c2 and extending transversely; and a third bent section c4 having one end communicable with the transverse section c3 and the other end communicable with a vertically-extending building sewer pipe P.

As one example, in the discharge socket 616C, the flow dividing section 26 and the delaying flow passage (28, 228) in the first embodiment are suitably usable in the second bent section c2. As another example, in the discharge socket 616C, the flow dividing section 526 and the delaying flow passage 528 in the third embodiment are suitably usable in the second bent section c2. As yet another example, in the discharge socket 616C, the flow dividing section 426 and the delaying flow passage 428 in the second embodiment are suitably usable in the transverse section c3. As still another example, in the discharge socket 616C, the flow dividing section 26 and the delaying flow passage 128 in the first embodiment are suitably usable in such a manner as to connect the second bent section c2 and the third bent section c4.

What is claimed is:

1. A flush toilet designed to be flushed using flush water to discharge waste, comprising:

a toilet main unit comprising a bowl portion for receiving waste, and a discharge trap pipe extending from a bottom of the bowl portion; and

a discharge conduit communicated with the discharge trap pipe,

wherein the discharge trap pipe comprises an inlet path connected to the bottom of the bowl portion, a rise path extending obliquely upwardly from a downstream end of the inlet path, and a fall path descending from a downstream end of the rise path,

wherein the discharge conduit is a resin member which is a separate component that is attached to the toilet main unit,

wherein the discharge conduit comprises

an upstream discharge conduit section;

a flow dividing section provided on a further downstream side than a downstream end of the upstream discharge conduit section;

a downstream discharge conduit section provided on a further downstream side than a downstream end of the flow dividing section; and

a delaying flow passage branched from the flow dividing section,

wherein:

the flow dividing section of the discharge conduit has a guide portion guiding flush water, and a flow rate of flush water guided to the delaying flow passage along the guide portion in flush water which a main stream

flows along a wall surface on a side of the rise path of the discharge trap pipe is greater than a flow rate of flush water guided to the downstream discharge conduit section without going through the delaying flow passage in the flush water which a main stream flows along a wall surface on a side of the rise path of the discharge trap pipe, and a flow rate of flush water guided to the delaying flow passage along the guide portion in the flush water which a main flow flows along a wall surface on a side of the rise path of the discharge trap pipe is greater than a flow rate of flush water guided to the delaying flow passage along the guide portion in the flush water which a main stream flows along a wall surface on a side opposite to the rise path of the discharge trap pipe, and

the delaying flow passage of the discharge conduit is configured such that flush water having flowed into the delaying flow passage along the guide portion of the flow dividing section is enabled to merge with a flush water flow reaching the flow dividing section at a timing after the inflow of the flush water to the delaying flow passage.

2. The flush toilet as recited in claim 1, wherein: the flow dividing section of the discharge conduit has a downward flow passage extending in an upward-downward direction,

and wherein the guide portion of the flow dividing section is formed on the side of the rise path of the discharge trap pipe from the downward flow passage of the flow dividing section, and between the downward flow passage and the delaying flow passage.

3. The flush toilet as recited in claim 2, wherein the guide portion of the flow dividing section extends obliquely downwardly to form an acute angle with respect to a vertical line.

4. The flush toilet as recited in claim 2, wherein the guide portion of the flow dividing section is formed on a peripheral wall defining the downward flow passage, on the side of the rise path of the discharge trap pipe, and forms a cutout portion on the peripheral wall on a side opposite to the rise path.

5. The flush toilet as recited in claim 2, wherein a connection portion between a peripheral wall defining the downward flow passage and the guide portion of the flow dividing section is formed to have a curved surface.

6. The flush toilet as recited in claim 2, wherein a bottom wall of the delaying flow passage is formed so as to protrude inside the flow dividing section to a position below and opposed to the guide portion of the flow dividing section.

7. The flush toilet as recited in claim 6, wherein an edge of the bottom wall of the delaying flow passage is located outward of the downward flow passage, in top view.

8. The flush toilet as recited in claim 2, wherein the downward flow passage of the flow dividing section is formed to have an introduction surface extending approximately vertically from an upper end of the downward flow passage to an upper end of the guide portion in upstream side from the guide portion.

9. The flush toilet as recited in claim 1, wherein a peripheral wall defining the downward flow passage of the flow dividing section is formed to have an introduction surface extending approximately vertically from an upper end of the downward flow passage to an upper end of the guide portion, and an inner peripheral surface of an outlet of the discharge trap pipe is formed so as to be approximately flush with the introduction surface of the flow dividing section of the discharge conduit.

10. The flush toilet as recited in claim 1, wherein the flow dividing section of the discharge conduit forms a transverse flow passage extending in a transverse direction, and wherein the guide portion of the flow dividing section is formed between the transverse flow passage of the flow dividing section and the delaying flow passage extending laterally from the transverse flow passage.

11. The flush toilet as recited in claim 10, wherein a connection portion between a peripheral wall defining the transverse flow passage and the guide portion of the flow dividing section is formed to have a curved surface.

12. The flush toilet as recited in claim 10, wherein a downstream surface of the delaying flow passage is formed so as to protrude inside the flow dividing section to a position downstream of and opposed to the guide portion of the flow dividing section.

13. The flush toilet as recited in claim 12, wherein an edge of the downstream surface of the delaying flow passage is located outward of the transverse flow passage, in side view as viewed from an upstream end of the transverse flow passage.
